CENTRALIZED TRAFFIC CONTROLLING
SYSTEM FOR RAILROADS

Neil D. Preston and Charles S. Bushnell, Rochester, N. Y., assignors to General Railway Signal Company, Rochester, N. Y.

Application November 30, 1932, Serial No. 645,037

31 Claims. (Cl. 177—353)

This invention relates to centralized traffic controlling systems for railroads, and more particularly to the communication part of such systems.

In such a system, railroad traffic is controlled from a central control office, and also the location of trains, as well as the condition of traffic controlling devices at remote locations, are indicated to the attendant at the control office. Such a system is supplemented by the well-known automatic block signal system and other local means, which are ordinarily provided to guard against unsafe train movements, improper operation of track switches or the like.

The switches and signals are distributed throughout the territory, but those located relatively near or adjacent each other, as well as the apparatus provided to govern these switches and signals, are conveniently referred to as comprising a field station. A communication system is provided to interconnect the control office with the several field stations, and is so organized that complete supervision is obtained by the operator, of the various signal and switch devices at the remote stations.

In accordance with the present invention, the communication system includes two line wires extending from the control office through the several field stations in series, which two line conductors are connected together at the last field station of the series in order to provide a normally closed line circuit. These two line conductors form a single circuit, used to select a desired one of the field stations, after which a relay or control device for each switch or signal at the selected station, may be actuated or conditioned for controlling their respective devices, thereby governing the traffic at the selected station. Such selection and control is referred to as transmission of controls.

The communication system is also used to transmit to the control office, indications of the positions of the switches and signals and for indicating the presence or absence of trains in particular track sections, as well as any other indications which may be useful in directing and supervising train movements, which indications are of course preceded by the registration in the control office of that particular field station that is transmitting. This function is automatically effected, when a new indication is ready to be transmitted to the control office and is conveniently referred to as transmission of indications.

The system is of the coded duplex type and is operated through cycles, during each of which, transmission of controls and transmission of in-

dications can occur separately or simultaneously. This feature is so incorporated in the system that duplex or two-way transmission can simultaneously occur to and from the same station, or to and from different stations.

When controls are transmitted, a station selecting code is first applied to the line for selecting the particular station desired, after which the controls are transmitted to the selected station by means of code impulses. When indications are transmitted, the field station transmitting such indications first sends a station registering code for registering that station in the office. Thereafter, the particular indications are transmitted to the control office, by means of an additional code and are displayed on indicator devices, such as lamps or the like, associated with the station sending.

For the transmission of controls, a predetermined number of impulses of selected polarities are placed on the line circuit for operating the apparatus at the control office and at the field stations, through a cycle of operations, irrespective of the character of the impulses, while the distinctive character of such impulses of a series included in the cycle determines the particular station to be selected and the controls to be transmitted to the selected station.

For the transmission of indications, the durations or lengths of time effected during the "off" and "on" impulse periods of a cycle are used to form a characteristic code combination which determines the particular station to be registered in the control office and the indications to be transmitted after such registration. The "on" periods refer to the periods when the line circuit is energized; while the "off" periods refer to the periods when the line circuit is de-energized.

One feature of the present invention relates to the manner in which both the time intervals between energized line periods and the time intervals of the energized line periods are varied in length, so as to double the indication transmission capacity over that ordinarily obtained. For example, in systems of this type, one energization or "on" period and one de-energization or "off" period of the line circuit has usually been designated as comprising a single step, with the field stations so arranged that indications are transmitted by distinctively changing or varying the condition of the line circuit once for each step. In the present embodiment, the condition of the line circuit is distinctively changed or varied twice during each step, once during the energized or

"on" period and once during the de-energized or "off" period.

A system arranged in this manner increases the capacity for the transmission of indications to substantially double the control transmission capacity of the system. This is particularly desirable in a centralized traffic controlling system, since it has been found in practice that the number of indications desired by the operator for proper information is substantially double the number of controls necessary for positioning the traffic governing devices under his supervision.

Another feature of the present invention relates to the manner in which controls are transmitted in coordination with the stepping relay operation without storing the polarity of the control impulses either in the control office or at the field station. This is accomplished in the control office by arranging the stepping relays and their contacts in such a way, that stepping is effected on the "on" periods and the half step relay is shifted on the "off" periods. In this connection the relays which select the polarity to be applied to the line circuit are maintained energized through contacts of a stepping relay which does not shift on the next energization of the line. A similar arrangement is used at the field station so that controls are registered on the "on" periods, through contacts of a stepping relay which does not shift on this "on" period.

Since the present invention is directed to the transmission of controls and double indications by means of a single circuit extending from the control office to the field stations, obvious economies in the construction and maintenance of the line are realized.

Other objects and advantages of the present invention will be hereinafter set forth in the specification and claims and shown in the drawings. The characteristic features will be explained more in detail in the following description of one embodiment of the invention, while various other characteristic features and advantages of the system comprising this invention, will be in part pointed out and in part apparent as the description progresses.

In describing the invention in detail, reference will be made to the accompanying drawings which illustrate, in a diagrammatic manner, the apparatus and circuits employed. Those parts having similar features and functions are designated in the different figures by like letter reference characters, generally made distinctive either by the use of distinctive exponents representative of their location or by the use of suitable preceding numerals representative of the order of their operation, and in which:

Fig. 1 illustrates the apparatus and circuits employed at the control office;

Fig. 2 illustrates the apparatus and circuits employed at one of the field stations.

GENERAL DESCRIPTION.

The single line circuit connecting the control office with the field stations is shown in the upper portion of Figs. 1 and 2 and the operation of the system may be conveniently followed by placing the drawing of Fig. 2 to the right of Fig.

1. Within the dotted rectangle, in the central upper portion of Fig. 2, the extension of the single line circuit through other stations is indicated. It will be understood that the line circuit extends through one or more stations, in addition to the one illustrated in Fig. 2 and that these additional stations have apparatus and circuit ar-

rangements practically the same as that shown in Fig. 2. As will be more specifically pointed out in the following description, the points of difference in the circuit connections at different field stations are the distinctive connections of the code jumpers and the contacts of the station relays ST (with suitable exponents and preceding numerals), so that a particular field station will be fully responsive only to the particular code assigned to that station.

For the purpose of simplifying the illustration and facilitating the explanation, various parts and circuits have been diagrammatically shown and certain conventional illustrations have been employed. The drawings have been made more with the purpose of making it easy to understand the principles and mode of operation, than with the idea of illustrating the specific construction and arrangement of parts that would be employed in practice. Thus, the various relays and their contacts are illustrated in a conventional manner, the use of symbols being employed to indicate the connections to the terminals of batteries or other sources of current instead of showing all of the wire connections to these terminals.

The symbols (+) and (-) indicate the positive and negative terminals, respectively, of suitable batteries or other sources of current; and the circuits with which these symbols are used always have current flowing in the same direction. The symbols (B+) and (B-) are employed to indicate the positive and negative terminals, respectively, of a suitable battery or other source of current having an intermediate tap (CN); and the circuits with which these symbols are used may have current flowing in one direction or the other, depending upon whether the terminal (B+) or (B-) is used in combination with the intermediate tap (CN).

No attempt has been made to show all of the apparatus employed, such as the total number of manual controls at the control office, the total amount of the equipment or its exact arrangement at the field stations, since these may vary to suit local conditions. The character of that apparatus illustrated in the typical control office and field station will now be considered.

Control office equipment.—As typical of the equipment located in the control office illustrated in Fig. 1, a control machine, having a group of control levers for each field station, is provided. A miniature track switch indicated by reference character *ts*, corresponds to a particular track switch in the field, and is considered to be representative of the actual track layout in the field. Various indicating lamps, such as *I*, or equivalent devices, together with apparatus and circuits to accomplish the desired operation of the system, are likewise provided. The portion of the control office apparatus illustrated in Fig. 1, shows more particularly that part of the control machine which is typical of the apparatus associated with a single field station having a track switch, a cross-over or the like, together with the common transmitting apparatus employed for controlling the circuit operation for all such stations.

This equipment for one track switch comprises a switch machine lever *SML*, a self-restoring starting button *SB*, the miniature track switch *ts* and the indication lamp *I*. Similarly, one or more signal control levers (not shown) would also be associated with the single field station apparatus, but in order to simplify the drawings

and description, these devices have been omitted. It is obvious that the control of a track switch, by means of a lever SML, may be considered as typical of the control of other traffic controlling devices.

The movement of the lever SML to one extreme position or the other, followed by the actuation of the starting button SB, results in the normal or reverse operation of the track switch, corresponding to lever SML at that field station which is associated with starting button SB, and this operation is controlled through the medium of the communication system of the present invention. The momentary actuation of the starting button SB is preferably stored by a storing relay (not shown) which, in turn, picks up the corresponding code determining relay CD of the associated station. Such control has been merely indicated in order to simplify the present disclosure.

The storing relays for each starting button and their corresponding code determining relays CD are so interconnected, that, irrespective of the number of storing relays energized simultaneously or in rapid succession, only one relay CD for one particular station may be picked up during one cycle of operations. This interlocking circuit connection is so arranged that if several storing relays are up at the same time, their corresponding relays CD will be picked up one at a time, during successive operating cycles, in an order predetermined by their relative locations in the bank of relays, all of which has been completely disclosed in the prior application of N. D. Preston et al., Ser. No. 455,304, filed May 24, 1930, Patent No. 2,129,183 dated September 6, 1938.

The control office includes a line relay F and a line repeating relay FP, both of which are normally picked up or energized during the normal period of rest of the system and also during the period of blank between successive operating cycles.

Slow acting line repeating relays SA and SAP are picked up at the beginning of each cycle and dropped at the end of each cycle. These two relays have such slow-acting characteristics that the pick-up time of each is relatively long compared to the pick-up time of the neutral relays F and FP, for example, but the pick-up time of these slow relays is relatively short in comparison with the time required for their release. The releasing or drop-away time of the relay SA is sufficiently long, so that its contacts remain in their picked up positions between successive impulses or during all "off" periods of a cycle, except the last "off" period, which is a comparatively long "off" period, for the purpose of returning the system to the normal period of rest, or period of blank.

Associated with the line relay F and its repeating relays is a bank of stepping relays, including stepping relays 1V, 2V, 3V and LV, together with a half step repeating relay VP, which are provided to mark off the successive steps of each cycle. An impulsing relay E is jointly controlled by the stepping relays and the half step relay, for cooperating with impulse repeating relay EP and pulsing relay PL to govern the opening and closing of the line circuit.

The polarity of the impulses applied to the line circuit from a battery B is determined by positive code sending relay PC and negative code sending relay NC. These two relays are controlled on the steps of an operating cycle in ac-

cordance with the station code and the controls to be transmitted for that particular cycle.

Relay EP, in addition to controlling the line pulsing relay PL, selects the polarity of the potential to be applied to the pilot relays as determined by the short and long "on" periods. Relay EPT selects the potential to be applied to the pilot relays as determined by the short and long "off" periods. A starting relay STR is picked up to initiate a cycle of operations, both when controls are to be transmitted due to the manual initiation of the cycle in the control office, and when indications are to be transmitted due to the automatic initiation of the cycle by a field station.

For the purpose of illustrating station registration and as typical of the pilot relay arrangement, pilot relays 1PF and 1PB are connected to the indication buses, so that they may or may not be picked up on the first step. Reference character 1PF indicates a first pilot relay, picked up through the front contact of line relay F during an "on" period. Reference character 1PB indicates a first pilot relay, picked up through the back contact of line relay F during an "off" period. Similarly, pilot relays 2PF and 2PB are picked up, or not, as determined by the indication code for the second step. Similarly, additional pilot relays (not shown) may be provided for additional steps up to the point where a sufficient number of codes for station registration have been provided. These pilot relays are of the two position polarized magnetic stick type, although it should be understood that any suitable type or arrangement may be provided for accomplishing the results obtained by this typical arrangement.

The indication receiving relays, such as for example relay 1RF, are also of the two position polarized magnetic stick type and are for storing the indications transmitted from the field stations. The particular indication receiving relay shown in Fig. 1 is merely typical of the circuit arrangement of all such relays. The reference character 1RF associated with this one relay, refers to its being operated through the front contact of relay E. Another indication receiving relay would have the reference character 1RB, meaning that this relay operates on the first step following station selection and that it is operated through the back contact of relay E.

The control office also includes various sources of current supply, bus wires, circuit connections, indicator lamps, terminal boards, overload protection and various other devices and apparatus which are necessary in railway signalling practice, but which have not been indicated in this disclosure.

Field station apparatus.—Since the apparatus and devices located at the field stations may vary according to local conditions, that illustrated in Fig. 2 is merely typical of all the field stations of the system. It will be understood that the arrangement of circuits and apparatus illustrated in Fig. 2 may be used at the first, or any other field station by merely arranging certain code jumpers and selective circuits for the desired code, but for convenience of description, the station illustrated in Fig. 2 is assumed to be the first field station and for this reason, the distinctive exponent ⁽¹⁾ has been employed in connection with the relays and other devices shown. A turn-out track is illustrated as connected to a main track by means of a track switch TS¹ which is op-

erated from one extreme locked position to the other by a suitable switch machine SM^1 .

The switch machine is controlled by a switch machine control relay SMR^1 , which is of the two position polar magnetic stick type, and which is positioned from the control office by means of the communication system disclosed herewith. The relay SMR^1 controls the operation of the switch machine by energizing its normal or reverse operating circuits from a local source of current in the field station in any suitable manner. This control preferably includes suitable approach locking means and other automatic signalling means, usually employed but not shown in order to simplify the present disclosure as much as possible. The switch machine SM^1 , while indicated as being controlled only from the control office, may employ a dual control selector in the well-known manner without in any way adding to, or detracting from, the present invention.

Suitable signals are associated with the track switch TS^1 for governing traffic over this section of track and these signals are provided with automatic signalling means, so that the traffic over this track switch may be coordinated with other sections of the track and other traffic controlling devices. These signals are capable of being controlled from the control office through the medium of the communication system of the present disclosure, by means of control relays operated from the control office in a manner similar to relay SMR^1 , but the complete circuit arrangement and description of this operation is omitted for the sake of simplicity. A detector track section, having a normally energized track circuit with the usual track relay T^1 and track battery, is also associated with the track switch TS^1 , for indicating the passage of trains over this section of track.

The communication part of the system at the field station includes a three-position biased-to-neutral polarized line relay F^1 , together with its quick acting line repeating relay FP^1 . Relay F^1 is normally positioned to the right by reason of the normally energized line circuit during the normal period. Relay FP^1 at the field station is normally de-energized. Slow acting relays SA^1 and SAP^1 , having characteristics similar to corresponding relays in the control office, are provided to define the bounds of each cycle of operation. Relay SA^1 is sufficiently slow in releasing when de-energized, so that it holds its armature attracted during all "off" periods (irrespective of their lengths) except the last, or "change to normal" period. The field station, likewise includes a bank of stepping relays $1V^1$, $2V^1$, $3V^1$ and LV^1 , together with the half step relay VP^1 , operating in a similar manner and in synchronism with the stepping relay bank in the control office.

For the purpose of illustrating the selection of a station, three station selecting relays $1ST^1$, $2ST^1$ and $3ST^1$, of the two-position polar magnetic stick type have been illustrated and it is to be understood that this arrangement for station selection is merely typical and that other suitable means may be employed.

A change relay CH^1 is provided to register a change in the traffic controlling devices at the station, so that the system will be initiated for the transmission of new indications, as required. Although this change relay is shown as being responsive only to a change in the position of track relay T^1 , it is to be understood that its holding stick circuit may be carried through any number of relays or other devices, so that it will register

a change in one or more of a large number of devices.

A change repeating relay CHP^1 , together with a lockout relay LO^1 , are employed at each field station in connection with the indication circuit to determine when this field station is to transmit new indications. Whenever the lockout relay LO^1 and the change repeating relay CHP^1 are properly positioned during a cycle of operations to permit the field station to transmit, a pulsing relay PL^1 is governed in accordance with the code jumpers and the indication contacts for this station, so that impulses of variable duration and time spacing are placed upon the single line circuit to register the station in the control office and to transmit the required indications.

Resistance R^1 is used for the purpose of compensating for the distance between the field stations and the control office. The last station, or the one at the end of the line, has no such resistance but the line wires are connected together as indicated within the dotted rectangle in the upper portion of Fig. 2. Other stations are provided with these resistance coils, the resistances of which are increased by a suitable amount to compensate for the line resistance, in such a way that the first station has a resistance coil R^1 with a maximum resistance, while the others are gradually decreased in resistance as they are located farther from the office. Relay PLT^1 is for the purpose of extending an otherwise normally short "off" period into a comparatively long "off" period.

The field station also includes suitable bus wires, circuit connections, code jumpers and other devices which are necessary in railway signalling practice but which have not been indicated in this disclosure for the sake of simplicity.

It is believed that the nature of this invention, its advantages and characteristics, may be best understood with further description being set forth in the manner of operation.

GENERAL OPERATION

The system of the present invention is shown in Figs. 1 and 2 in the normal or condition of rest, from which it may be initiated into a cycle of operations, either by a manual operation at the control office or an automatic operation at any of the field stations, whenever there are new controls or new indications, respectively, to be transmitted. In the event that there are controls ready for transmission to several different field stations at substantially the same time, they are transmitted to the different field stations on separate cycles of operations, one station for each cycle. Likewise, if several field stations have indications to be transmitted at substantially the same time, they are transmitted to the control office, one station at a time on separate operating cycles.

It may happen that there are new controls and new indications ready for transmission at a given time and in this event controls are transmitted simultaneously with indications. On such occasions, indications may be transmitted from the same field station to which controls are transmitted, or they may be transmitted from some other field station during the same cycle of operations.

Irrespective of whether the cycle is for transmission of controls and/or the transmission of indications, a predetermined number of impulses is applied to the line circuit, to accomplish the

5 synchronous operation of the stepping relays at the control office and at the field stations. These impulses are time spaced, the intervals between impulses being of variable durations and the periods during which the line is energized being also of variable durations.

When a cycle of operation is initiated for the transmission of controls, the character of the impulses applied to the line is determined by the 10 particular station to be selected and the particular controls to be transmitted to the selected station, in accordance with the code jumper connections and the positions of the control levers respectively for that station.

15 When a cycle of operation is initiated for the transmission of indications alone, the character of the impulses applied to the line circuit is the same for all impulses and this particular combination does not effect the selection of any field 20 station, but merely functions to cause the stepping relays in the control office and at the field stations to be operated in synchronism. When such a cycle of operations is initiated from a field station for the transmission of indications, 25 the line circuit is energized and de-energized with a series of impulses of a single character. Since this results in a combination of a distinctive character being applied to the line circuit, when no station is to be selected for transmission 30 of controls, this particular code is not effective to select a station and it is conveniently referred to as a phantom code.

If, while transmission of controls is taking place, no indications are being transmitted, the 35 de-energized, or "off", periods of the line circuit are all of comparatively short duration and the energized, or "on", periods of the line circuit are of comparatively long duration. Indications are transmitted from the field stations to the office 40 over the single line circuit, by predetermining whether the "off" periods will be short (normal) or long (abnormal) and predetermining whether the "on" periods will be long (normal) or short (abnormal). The combinations of these short 45 and long "off" and "on" periods are effective to determine the station to be registered in the control office and thereafter display the indications from the registered station.

The line relay in the control office is normally 50 operated and those at the field stations are normally positioned to the right, by means of current flowing over the line circuit, from battery B in the control office, through the normally energized, positive control relay PC.

55 When controls or indications are to be transmitted, the line circuit is momentarily opened and the battery connection reversed, after which the line circuit is energized by current from the battery flowing in a reverse direction from normal, which is effective to pick up the line relays at the field stations and position them to the left. This first energized period is conveniently referred to as the initiating period, during which certain relays are conditioned, as will be later 60 described in detail.

The momentary interruption of the line and the reversal of the battery connection to the line circuit is also conveniently referred to as the lockout period, since it is during this period that 65 one station is effectively connected to the communication system for the transmission of indications, to the exclusion of all other stations.

After the initiating period, the system continues through a complete cycle of operations, consisting of a number of "off" and "on" periods,

this number being determined by the number of steps required and this number of steps, in turn, being governed by the size of the system. After the last "on" period, a comparatively long "off", or de-energized period, is effective to condition 5 the relays for changing to normal, or the period of blank. After this "off" period, the line is energized by current from battery B, in what may be conveniently termed a (+) direction, since the positive control relay is picked up and the 10 line relays F^1 , F^2 , etc., at the stations are positioned to the right. This is the normal period or period of blank.

In the system of the present invention, the 15 stepping relays $1V$, $2V$, etc., in the control office and $1V^1$, $2V^1$, etc., at each field station operate in synchronism throughout a cycle, being picked up during the "on" periods and dropped at the end of the cycle. The half step relays VP in the control office and at the field stations are likewise 20 operated in synchronism throughout a cycle, being shifted during the "off" periods, that is, they pick up at the start of the odd "off" periods and drop at the start of the even "off" periods. The "on" periods are those periods 25 during the cycle, when the communication line is energized and the "off" periods are those periods during the cycle, when the communication line is de-energized.

For convenience in describing the operation of 30 the present invention, an operating cycle is divided into periods as shown in the following table:

1. Normal or period of blank. "On" (+).	35
2. Initiating and lockout period. Manual start from control office. Automatic start from field station. "On" (+) shifting to (-).	40
Associates sending station with control line circuit and locks out all other stations.	45
3. Conditioning period. Conditions lockout, line and line repeating relays. Long "on" (-).	50
4. First "off" period. Relays VP and VP^1 picked up. Control No. 1 conditioned. "Off" indication No. 1 conditioned.	55
5. First "on" period. Relays $1V$ and $1V^1$ picked up. Control No. 1 executed. "Off" indication No. 1 executed. "On" indication No. 1 conditioned.	60
6. Second "off" period. Relays VP and VP^1 dropped. Control No. 2 conditioned. "On" indication No. 1 executed. "Off" indication No. 2 conditioned.	65
7. Second "on" period. Relays $2V$ and $2V^1$ picked up. Control No. 2 executed. "Off" indication No. 2 executed. "On" indication No. 2 conditioned.	70
8. Third "off" period. Relays VP and VP^1 picked up. Control No. 3 conditioned. "On" indication No. 2 executed. "Off" indication No. 3 conditioned.	75
9. Third "on" period. Relays $3V$ and $3V^1$ picked up. Control No. 3 executed. "Off" indication No. 3 executed. "On" indication No. 3 conditioned.	

10. Fourth "off" period.
Relays VP and VP¹ dropped.
Control No. 4 conditioned.
"On" indication No. 3 executed.
5 "Off" indication No. 4 conditioned.
11. Fourth "on" period.
Relays LV and LV¹ picked up.
Control No. 4 executed.
"Off" indication No. 4 executed.
10 "On" indication No. 4 conditioned.
12. Change to normal period (off).
"On" indication No. 4 executed.
Restores various relays to normal.
15 Long "off". Followed by period of blank.

DETAILED OPERATION

Normal period of rest.—With the communication part of the centralized traffic controlling system, with which this invention is concerned, at 20 rest, all of the relays in the control office and at the field station are in their normal or de-energized positions except relays F, F¹, FP, PC, EP, CH¹, CHP¹ and T¹.

Relay F is held up and relay F¹ is positioned to 25 the right by current in the circuit extending from the positive terminal of battery B, front contact 26 of relay PC, back contact 27 of relay NC, winding of relay F, back contact 28 of relay PL, line conductor 1, winding of relay F¹, back contact 25 30 of relay PL¹, through other field stations and including their relays such as F² and back contacts of relays such as PL², conductor 8 closed at the last station, line conductor 9, back contact 29 of relay NC, front contact 30 of relay PC and 35 negative side of battery B.

Relay FP is energized over a circuit extending from (+), front contact 18 of relay F and winding of relay FP to (—). Relay PC is energized over a circuit extending from (+), back contact 40 13 of relay VP, back contact 14 of relay 3V, back contact 15 of relay 1V, back contact 17 of relay STR, (+) bus and winding of relay PC to (—). Relay EP is energized over a circuit extending from (+), back contact 37 of relay E and winding 45 of relay EP to (—).

Relay CH¹ is energized over a circuit extending from (+), front contact 153 of relay T¹, conductor 152, front contact 197 of relay CH¹ and lower winding of relay CH¹ to (—). Relay CHP¹ is 50 energized over a circuit extending from (+), back contact 166 of relay PLT¹, front contact 198 of relay CHP¹ and upper winding of relay CHP¹ to (—). Track relay T¹ is normally energized by means of a circuit (not shown) connected to the 55 normally energized track section.

Manual starting.—It will be assumed that the system is in its normal condition and that the operator desires to transmit controls to a particular field station. Control lever SML, indicated in 60 Fig. 1, is typical of other control levers provided. When the starting button SB, associated with the desired station, is actuated, a suitable storing relay is positioned and the CD relay, associated with the desired station, is immediately picked up. 65 However, such CD relays for several stations are so interconnected, that if several starting buttons are simultaneously operated or operated in quick succession, only one CD relay is picked up at any one time. Thus, these CD relays are picked 70 up successively for successive cycles of operations. The interconnecting circuits for accomplishing this selective operation are not disclosed in this embodiment, but may be of the arrangement fully shown and described in the prior application Ser. 75 No. 455,304, above mentioned.

In considering the operation of the present invention, it will be understood that the actuation of starting button SB, shown in Fig. 1, causes the actuation of the corresponding CD relay, only one of which can be up at any one time. The actuation of the starting button SB, in picking up its corresponding CD relay, also picks up starting relay STR and this relay is effective to initiate the cycle of operations. The circuit for picking up relay STR extends from (+), back contact 10 10 of relay SA, front contact 11 of relay CD, front contact 12 of relay FP and winding of relay STR, to (—). Relay STR completes a stick circuit for itself extending from (+), back contact 13 of relay VP, back contact 14 of relay 3V, back contact 15 of relay 1V, front contact 16 of relay STR and winding of this relay, to (—).

This stick circuit for relay STR, including back contact 13 of relay VP, is opened during the first 20 "off" period when relay VP is picked up, which results in the release of relay STR. Relay STR can not again be picked up during this same cycle, since its energizing circuit will be open at back contact 10 of relay SA, which is held up until the end of the cycle.

The picking up of relay STR opens the normally energized circuit of relay PC at back contact 17 of relay STR. Front contact 17 of relay STR switches the above described circuit, extending from (+), through back contact 13 of relay 30 VP, to the winding of relay NC and this relay is immediately picked up.

During the interval between the dropping of relay PC and the picking up of relay NC, the line circuit is deenergized, which may allow relays F 35 in the control office and F¹ at the field station to be dropped, but this interval is of such short duration that the circuits which these relays close are not effective to pick up other relays, such as PLT¹ at the field station. The release of relay 40 PC and the actuation of relay NC results in reversing the connection of battery B to the line circuit, which operates the line relays at the stations, (such as F¹ indicated in Fig. 2) to the left.

This brings the cycle of operations into the 45 conditioning period and results in picking up relays F, FP, SA and SAP at the control office and relays F¹, FP¹, SA¹ and SAP¹ at the field station. The circuit for energizing relay FP in the control office is from (+), front contact 18 of 50 relay F and winding of relay FP, to (—). Before relay SA is picked up, relay FP is held up through back contact 21 of relay SA and front contact 25 of relay FP. The circuit for picking up the SA relay extends from (+), front contact 19 of relay 55 NC, front contact 20 of relay FP and winding of relay SA, to (—). The circuit for picking up the SAP relay extends from (+), front contact 21 of relay SA and winding of relay SAP, to (—).

The circuit for picking up relay FP¹ at the field 60 station extends from (+), contact 122 of relay F¹, now in its left hand dotted position, and winding of relay FP¹, to (—). The circuit for picking up relay SA¹ extends from (+), front contact 123 of relay FP¹, and winding of relay SA¹, to (—). 65 The circuit for picking up relay SAP¹ extends from (+), front contact 124 of relay SA¹ and winding of relay SAP¹, to (—).

Polarity selection of impulses.—When the system is initiated into a cycle of operations from 70 the control office, resulting in the operation of starting relay STR, the first impulse placed upon the control line is (—), as indicated in the initiating period of the above table. This is because relay PC is dropped and relay NC is picked up 75

each time the control office initiates a cycle of operations.

During the initiating period, when relay PC is released and relay NC is picked up, the battery connection to the line is reversed, which results in holding relay F in the control office and actuating relays F¹, F², etc., at the field stations to their left hand positions. This application of current from battery B to the line circuit causes the system to go through various relay operations, but the description of these operations will be omitted at present, it being assumed that the control line circuit is impulsed by means of back contact 28 of relay PL, and that this impulsing circuit results in the stepping relay operation.

During the conditioning period, the operation of relay SAP closes a circuit for picking up relay E, extending from (+), front contact 31 of relay SAP, back contacts 32, 33, 34 and 35 of the four stepping relays in series, back contact 36 of the half step relay VP and winding of relay E, to (-). The operation of relay E closes a circuit for picking up relay EPT extending from (+), front contact 37 of relay E and winding of relay EPT, to (-). Relay EPT completes a stick circuit for itself as long as relay F is operated, extending from (+), front contact 38 of relay F, front contact 39 of relay EPT, and winding of relay EPT, to (-).

It will be recalled that the line is energized during this, the conditioning period, and by referring to the above table it will be noted that this period is a long "on". This is for the reason that the line will remain closed until slow acting relay EP is dropped, after its circuit is interrupted at back contact 37 of relay E, which is now actuated. When relay EP releases its armature, a circuit is closed for actuating relay PL extending from (+), back contact 40 of relay EP and winding of relay PL, to (-). The actuation of relay PL and the resulting deenergization of the line advances the system into the first "off" period.

When the line is deenergized, by relay PL opening its back contact 28, relay F is released and since the stick circuit of relay FP, through its own front contact 25, is now interrupted at back contact 21 of relay SA, the opening of front contact 18 of relay F results in the release of relay FP. A circuit is now closed for picking up the half step relay VP, extending from (+), front contact 31 of relay SAP, back contact 41 of relay FP, back contact 42 of relay 1V and winding of relay VP, to (-). Relay VP closes a stick circuit for itself, which is effective as long as relay 1V is down and which extends through its front contact 43 and the remainder of the circuit just described.

With the code jumper 44 connected as shown, control No. 1 is conditioned by the actuation of relay PC and the release of relay NC. Relay NC is dropped when its circuit is interrupted, at back contact 13 of relay VP and relay PC is picked up over a circuit extending from (+), front contact 13 of relay VP, back contact 45 of relay 2V, No. 1 control bus 46, front contact 47 of relay CD, code jumper 44 and winding of relay PC, to (-). The release of relay NC and the actuation of relay PC, results in the preselection of a (+) impulse for the next, or first "on" period, and the connection of the line circuit to battery B, through front contacts of relay PC and back contacts of relay NC, is in such a direction that relay F¹ of Fig. 2 will be actuated to its right hand position.

The control of the NC and PC relays is effected

during other "off" periods, by means of other code jumpers, such as 48 and 49. Thus, in the second "off" period, relay VP will be dropped and since relay 1V will be up, (picked up during the first "on" period), a circuit is effective for picking up relay NC, extending from (+), back contact 13 of relay VP, back contact 14 of relay 3V, front contact 15 of relay 1V, No. 2 control bus 50, front contact 51 of relay CD, jumper 48 and winding of relay NC, to (-). The actuation of relay NC and the release of relay PC, (since the circuit of relay PC is incomplete during this period) results in preselecting a (-) code for the second "on" period.

During the third "off" period relay VP will again be picked up and relay 2V will be up, (being picked up during the second "on" period), which closes a circuit for conditioning the No. 3 control, extending from (+), front contact 13 of relay VP, front contact 45 of relay 2V, No. 3 control bus 52, front contact 53 of relay CD, code jumper 49 and winding of relay PC, to (-). Since this results in the actuation of relay PC and the release of relay NC, a (+) code impulse is preselected for the third "on" period.

During the third "on" period, relay 3V is picked up and during the fourth "off" period relay VP is dropped. Control No. 4 is conditioned during the fourth "off" period by means of a circuit extending from (+), back contact 13 of relay VP, front contact 14 of relay 3V, No. 4 control bus 54, front contact 55 of relay CD, and contact of switch machine lever SML, to either the (+) bus or the (-) bus, as determined by the position of lever SML. If this lever is connected with the (+) bus, as indicated in Fig. 1, the code impulse of the fourth "on" period will be (+), because relay PC will be picked up and relay NC will remain normal.

It will be apparent that the code jumpers 44, 48 and 49, connected as shown in Fig. 1, result in the selection of a station having a code combination (+) (-) (+). It will be obvious that, while only one step is used for selecting a control lever, such as SML, by means of code bus 54, additional steps may be provided for selecting additional control devices, by way of other code buses similar to 54.

From the above it will be seen that the impulses applied to the line circuit always begin with a (-) and are followed by a combination of (+) or (-) impulses, dependent upon the code jumper connections and the control lever positions, rendered effective by the particular code determining relay CD which is picked up during a particular cycle. Also, the character or polarity of the impulses in the line circuit is selected by polarity determining relays, PC for a positive impulse and NC for a negative impulse and that these polarity determining relays are positioned during the "off" periods, in readiness for the application of the preselected polarity during the following "on" periods.

Operation of stepping relays.—It has been explained that the line circuit is normally energized with what may be conveniently termed a (+) polarity, since relay F¹ at the field station is actuated to its right hand position during the normal period. It has also been explained that the polarity applied to the line circuit during the conditioning period is (-), which results in actuating relay F¹ at the field station to its left hand position. It has also been pointed out that the impulses following the conditioning impulse period vary in polarity. Irrespective, however, of

the particular polarity with which the line circuit is energized, relays F and FP in the control office are energized by means of circuits above pointed out. Also, irrespective of the polarity of the line 5 circuit impulses which results in actuating relay F¹ at the field station to different positions, relay FP¹ repeats the actuation of relay F¹, either by means of the circuit extending through contact 122 of relay F¹, direct to the winding of relay FP¹, 10 or by means of the circuit extending through contact 122 of relay F¹ in the right hand position and front contact 157 of relay SAP¹.

At the beginning of the transmitting part of the cycle, marked off by the operation of relays 15 SA and SAP in the control office, relays SA¹ and SAP¹ at the field station shown in Fig. 2, and other similar relays at other field stations are picked up. The half step relay VP in the control office is picked up when the line is deenergized 20 at the beginning of the first "off" period, this circuit having been described. The half step relays, VP in the control office and VP¹ at the field station, are picked up and dropped alternately by successive energizations of the line circuit, that is, 25 they are picked up during the odd "off" periods and are dropped during the even "off" periods. The stepping relays in the control office and at the field station, each take one step for each successive energization of the line circuit, that is, 30 relays 1V and 1V¹ pick up during the first "on" period, relays 2V and 2V¹ pick up during the second "on" period, etc.

Although the stepping relays at the field station operate by means of similar circuits, the description will be directed to those in the control office 35 (Fig. 1). After relay VP is picked up during the first "off" period, as above described, the system advances into the first "on" period by means of a closure of the line circuit, details of which will 40 be later described.

During the first "on" period, relays F and FP are picked up and a circuit is closed for actuating relay 1V extending from (+), front contact 58 of relay SAP, front contact 59 of relay FP, front 45 contact 60 of relay VP, back contact 61 of relay 2V and winding of relay 1V, to (-). Relay 1V, in operating, closes a stick circuit for itself extending from (+), front contact 58 of relay SAP, front contact 62 of relay 1V and winding of relay 50 1V, to (-). It will be understood that this stick circuit for relay 1V, as well as the stick circuit for the other stepping relays, is effective to hold the stepping relays in their operated positions, after 55 they are picked up, until the end of the cycle.

Although the above described stick circuit for relay VP is opened at back contact 42 when relay 1V is actuated, the VP relay is energized during this period over another circuit extending through front contact 41 of relay FP and front contact 60 63 of relay VP.

Upon the next deenergization of the line circuit, which advances the system into the second "off" period, the circuit of relay VP, extending through front contact 41 of relay FP, is interrupted and since its circuit through back contact 42 of relay 65 1V is now open, relay VP is released.

The system is next advanced into the second "on" period, by means of a closure of the line circuit and relay 2V is picked up over a circuit extending from (+), front contact 58 of relay SAP, front contact 59 of relay FP, back contact 60 of relay VP, back contact 64 of relay 3V, front contact 65 65 of relay 1V and winding of relay 2V, to (-). As soon as relay 2V is operated, it closes a

stick circuit for itself to stick conductor 66, by way of its front contact 67.

The following deenergized condition of the line circuit, which is the third "off" period, results in again picking up relay VP by means of a circuit 5 extending from (+), front contact 31 of relay SAP, back contact 41 of relay FP, back contact 68 of relay 3V, front contact 69 of relay 2V and winding of relay VP, to (-). Relay VP closes a stick circuit for itself, through its front contact 10 43, which is independent of the above described pick-up circuit for this relay through back contact 41 of relay FP.

The system is now advanced into the third "on" period by a closure of the line circuit. This results in operating relay 3V by means of a circuit 15 extending from (+), front contact 58 of relay SAP, front contact 59 of relay FP, front contact 60 of relay VP, front contact 61 of relay 2V and winding of relay 3V, to (-). Relay 3V operates 20 and closes an obvious stick circuit for itself, by way of its front contact 70.

The system advances into its fourth "off" period when the line is next deenergized. Relay VP is then dropped because its stick circuit, through 25 its front contact 63, is interrupted at front contact 41 of relay FP and its stick circuit, through its front contact 43, is interrupted at back contact 68 of relay 3V.

The system is advanced into the fourth "on" 30 period when the line circuit is next energized. Relay LV is picked up during this period over a circuit extending from (+), front contact 58 of relay SAP, front contact 59 of relay FP, back contact 60 of relay VP, front contact 64 of relay 3V 35 and winding of relay LV, to (-). Relay LV, in operating, closes an obvious stick circuit for itself by way of its front contact 71.

Since the fourth "on" impulse is the last in the cycle of operations for the present embodiment, the next deenergization of the line circuit continues until the system returns to its normal period. This condition is referred to as the "change to normal" period, which is an "off" 40 period because the line circuit is open. During 45 this period, relay LV is up and relay VP is down, therefore, a circuit is effective for holding relay E in its operated position, extending from (+), front contact 31 of relay SAP, front contact 32 of relay LV, back contact 36 of relay VP 50 and winding of relay E, to (-). Relay E, in its operated position, causes the release of relay EP and the actuation of relay PL, by means of circuits above described. Relay PL holds the line circuit open, at its back contact 28 and 55 since there are no additional steps required in this embodiment of the invention, relays E and PL are not immediately dropped to close the line, which results in a long "off" period.

Since relays F and FP are now down for a comparatively long interval, relays SA and SAP are released in turn. When relay SAP opens its contact 58, the stick circuits of all stepping relays are interrupted and they are released. Relay SAP also opens the circuit of relay E, at its front 60 contact 31, which results in the release of the E relay. A circuit is now closed through back contact 37 of relay E for picking up relay EP. The actuation of relay EP opens the circuit of relay PL, which drops and closes the line circuit 65 at back contact 28. This advances the system into the normal period and it will be obvious that the line is again energized with a (+) impulse, because relay PC is picked up over the previously described circuit, through back contacts 13, 14, 70 75

15 and 17 of relays VP, 3V, 1V and STR respectively.

In this particular case, where an even number of stepping relays have been shown, the VP 5 relay is already deenergized when the system advances into the "change to normal" period; but it will be understood that when an odd number of stepping relays are used, the opening of front contact 31 of relay SAP results in the release 10 of relay VP.

It is to be understood that these circuit connections may be extended for as many steps as desired, with the pick-up and stick circuits of the stepping relays and the half step relay extended 15 in an obvious manner. As already mentioned, the stepping relays and the half step relays at the field stations operate in a substantially identical manner and for this reason it is not believed necessary to describe the operation of these relays 20 in detail.

Impulsing of the line for controls.—During a cycle of operations for the transmission of controls alone, the "off" periods are short and the "on" periods are long. It will now be assumed 25 that the stepping relays 1V, 2V, 3V and LV and the half step relay VP operate, as above described and an explanation will be given of the circuits which are effective during this stepping relay operation, to impulse the line circuit.

30 As above explained, the line is normally energized with a (+) potential, and during the conditioning period it is energized with a (−) potential for picking up relays FP¹, SA¹ and SAP¹ at the stations. During this period, relays FP, SA 35 and SAP in the control office are picked up.

The conditioning period is always a long "on" because the release of slow relay EP of Fig. 1 must occur after relay E picks up before PL can be picked up for opening the line circuit. Opening 40 the line advances the system into the first "off" period and relay VP is actuated, opening the circuit of relay E at back contact 36 of relay VP, which releases relay E, picks up relay EP and releases relay PL. This closes the line and extends the cycle into its first "on" period. It will be noted that the "off" period is short because, when the line is opened at the start of this period, it is closed up again as soon as relays F and FP drop, relay VP picks up, relay E drops, relay EP picks up and relay PL drops.

During the first "on" period relays F, FP and 45 1V are picked up in a manner previously described and relay E is picked up over a circuit extending from (+), front contact 31 of relay SAP, back contacts 32, 33 and 34 of stepping relays LV, 3V and 2V respectively, front contact 35 of relay 50 1V, front contact 36 of relay VP and winding of relay E, to (−). The operation of relay E opens the circuit of relay EP and this latter relay must drop its armature before relay PL is picked up to again open the line. Since relay EP is slow to release, the "on" period is of long duration.

The operation of relay PL opens the line, which 55 advances the system into the second "off" period and during this period relay VP is dropped as previously described. This results in the release of relay E, the picking up of relay EP and the dropping of relay PL for again closing the line circuit, which advances the system into the second "on" period.

70 From the above it can be seen that relay EP is provided to prolong the energized or "on" periods. It is also believed that it will be obvious 75 how the line is impelled by the picking up and

release of these various relays on additional steps, in a manner similar to that above explained.

5 *Station selection for controls.*—For the transmission of controls, the conditioning impulse of each cycle is always (−), while the following impulses are (+), or (−) in accordance with the particular code jumper connections and control lever positions which are effective for that cycle. It will be obvious, by referring to the circuits of Figs. 1 and 2, that these impulses are received at all field stations, since relay PL¹ is not picked up during transmission of controls, which results in the line circuit being extended from station to station, through back contacts similar to back contact 125 of relay PL¹.

10 15 For convenience in describing the operation of a field station, reference will be made to the circuit of Fig. 2, which illustrates a typical field station in detail and which may be considered as the first station or the one nearest the control office. 20 The application of the first (−) impulse to the line circuit causes the line relay F¹ to actuate its contacts to the left hand dotted position closing a circuit for picking up relay FP¹ extending from (+), contact 122 of relay F¹ and winding of relay FP¹, to (−). Relay FP¹, in turn, closes a circuit for picking up relay SA¹ extending from 25 (+), front contact 123 of relay FP¹ and winding of relay SA¹, to (−). It has been pointed out that this first (−), or conditioning impulse, is 30 long for the purpose of picking up the slow acting relays. The operation of relay SA¹ closes a circuit through its front contact 124 for picking up relay SAP¹.

35 After the conditioning period, the system advances into the first "off" period, completing a circuit for picking up relay VP¹ extending from (+), front contact 126 of relay SAP¹, back contact 127 of relay FP¹, back contact 128 of relay 40 1V¹, and winding of relay VP¹, to (−). Upon the picking up of the contacts of relay VP¹, its temporary stick circuit is closed from (+), front contact 126 of relay SAP¹, front contact 129 of relay VP¹, back contact 128 of relay 1V¹ and winding of relay VP¹, to (−). 45

The system now advances into the first "on" period with relays F¹ and FP¹ picked up, the latter relay completing a holding stick circuit for relay VP¹, from (+), front contact 126 of relay SAP¹, front contact 127 of relay FP¹, front 50 contact 121 of relay VP¹ and winding of relay VP¹, to (−). This holding stick circuit is completed before the temporary stick circuit, including back contact 128 of relay 1V¹, is interrupted when relay 1V¹ is picked up during this 55 period, because relay 1V¹ cannot pick up until relay FP¹ is actuated to close its front contact 120. With relay FP¹ actuated, the circuit for picking up relay 1V¹, during the first "on" period, is completed from (+), front contact 130 60 of relay SAP¹, front contact 120 of relay FP¹, front contact 131 of relay VP¹, back contact 132 of relay 2V¹ and winding of relay 1V¹, to (−). As soon as relay 1V¹ picks up, it closes a stick circuit for itself including front contact 130 of 65 relay SAP¹ and front contact 133 of relay 1V¹. It is not considered necessary to explain the further stepping operations at the field station, since these operations are identical with those explained in connection with the control office. 70

The first stepping relay 1V¹ is picked up during the first "on" period, which is the period when control No. 1 is executed, but the circuit over which control No. 1 is executed does not include a contact of the first stepping relay. The 75

half step relay VP^1 was picked up during the first "off" period, which is the conditioning period for control No. 1, but the circuit for executing the No. 1 control is not complete until polar relay F^1 is actuated. In other words, the polarity of the first code impulse is preselected in the control office during the first "off" period and since the relay VP^1 is picked up during this period, this first code impulse is executed during the following "on" period by the operation of polar relay F^1 .

For example, at the field station illustrated in Fig. 2, the first station relay $1ST^1$ is energized over a circuit extending from (+), contact 135 of relay F^1 (actuated to its right hand position because control No. 1 preselected by code jumper 44 in Fig. 1 was (+)), front contact 136 of relay VP^1 , back contact 137 of relay $2V^1$, No. 1 (+) control bus 134 and upper winding of relay $1ST^1$, to (-).

If the first impulse had been (-) (because the No. 1 control bus 46 of Fig. 1 was connected by way of jumper 44 to relay NC instead of relay PC) the actuation of relay F^1 would have been to the left, closing a circuit through its contact 135 in the left hand dotted position, front contact 139 of relay VP^1 , back contact 140 of relay $2V^1$, No. 1 (-) control bus 141 and lower winding of relay $1ST^1$, to (-). It will be readily understood how the selection of No. 1 (+) bus 134 of No. 1 (-) bus 141 by relay F^1 , results in positioning polar relay $1ST^1$ to its right or left hand position respectively.

During the second "on" period, relay $2V^1$ is picked up and relay F^1 is actuated to its left hand position by a (-) impulse, closing a circuit from (+), contact 135 of relay F^1 in its left hand dotted position, back contact 139 of relay VP^1 , back contact 142 of relay $3V^1$, front contact 143 of relay $1V^1$, No. 2 (-) control bus 144 and lower winding of relay $2ST^1$, to (-). If this impulse in the line should be (+) instead of (-), relay F^1 would close its contact 135 in its right hand position, extending the circuit by way of back contact 136 of relay VP^1 , back contact 145 of relay $3V^1$, front contact 146 of relay $1V^1$, No. 2 (+) control bus 147 and upper winding of relay $2ST^1$, to (-). The selection of bus 144 or 147 results in the selection of the position in which relay $2ST^1$ will be placed during the second "on" period.

During the third "on" period, relay F^1 will be positioned to select a circuit through its contact 135 in its right hand position, (+) impulse, front contact 136 of relay VP^1 , front contact 137 of relay $2V^1$, No. 3 (+) control bus 148 and upper winding of relay $3ST^1$, to (-). Or if relay F^1 is positioned to the left, a circuit through its left hand dotted position contact 135 is extended through front contact 139 of relay VP^1 , front contact 140 of relay $2V^1$, No. 3 (-) control bus 149 and lower winding of relay $3ST^1$, to (-).

From the above it will be evident that there are a plurality of code determining relays and a set of code jumpers in the control office, one of which relays may be effective to determine the character of the impulses of any particular cycle. During the first part of the cycle, the station selecting relays similar to $1ST^1$, $2ST^1$ and $3ST^1$ at the field stations are positioned in accordance with the connections of the code jumpers effective for that particular cycle of operations. At each field station a different circuit is selected through the station selecting relays, because each station requires the transmission of a distinctive code

and this code is effective to position the station selecting relays in the proper positions, only at the station to be selected for completing circuits through their contacts.

When the fourth control is executed during the fourth "on" period, all the stepping relays will be up and the VP relay will be down. A circuit is now effective to position switch machine relay SMR^1 , which is a polar magnetic stick relay and which closes circuits in its two operated positions for selectively operating the switch machine SM^1 , to selectively operate the track switch TS^1 . If this control impulse is (+), relay F^1 extends the circuit from (+), its contact 135 in its right hand position, back contact 136 of relay VP^1 , front contact 145 of relay $3V^1$, No. 4 (+) control bus 150, contacts of station selecting relays $1ST^1$, $2ST^1$ and $3ST^1$ in series, and upper winding of relay SMR^1 , to (-). This positions relay SMR^1 to its right hand position for actuating switch machine SM^1 to its normally locked position.

If this impulse in the line circuit is (-), relay F^1 closes a circuit from (+), through its contact 135 in its left hand dotted position, back contact 139 of relay VP^1 , front contact 142 of relay $3V^1$, No. 4 (-) control bus 180, contacts of station selecting relays $1ST^1$, $2ST^1$ and $3ST^1$ in series and lower winding of relay SMR^1 , to (-). This latter circuit results in positioning relay SMR^1 to the left for actuating switch machine SM^1 to its reverse locked position.

With the use of only three station selecting relays, as shown in Fig. 2, eight different code combinations are possible, seven of which may be used for station selection, while the eighth is conveniently referred to as the phantom station code call. It will be understood that the code combination for the field station, illustrated in Fig. 2, is (+)(-)(+), as determined by code jumpers 44, 48 and 49 of Fig. 1 being connected to buses (+)(-)(+). Assuming that a (+) impulse actuates a station selecting relay to the right, it will be understood that the code combination predetermined by the code jumper connections of Fig. 1, position the station selecting relays $1ST^1$, $2ST^1$ and $3ST^1$ in the positions shown in Fig. 2, so that circuits are completed for succeeding impulses which will be effective to position control relays, such as SMR^1 of this particular station. Also, that control relays, such as SMR^1 at any other station, will not be selected since the station selecting relays at any other station will not have circuits completed to control relays in the positions indicated by the station selecting relays of Fig. 2.

It is obvious that any number of additional steps may be provided for transmitting additional controls to the field station illustrated in Fig. 2, for governing the signals and such other devices as may be required.

End of operating cycle.—It has been explained that relays F , FP , SA and SAP and all stepping relays in the control office are released during the "change to normal" period, which follows the fourth "on" period. It will be recalled that this was a long "off" period resulting in the release of relays E and PL and the picking up of relay EP . This long "off" period also results in relays F^1 , FP^1 , SA^1 and SAP^1 being dropped and when relay SAP^1 opens its front contact 130, the stick circuit of the stepping relays is interrupted and they are released.

Simultaneously with the dropping away of the stepping relays in the control office, the par-

ticular code determining relay CD, which was picked up during the cycle, is deenergized, so that the next code determining relay in order may be effective at the beginning of the next cycle, if its corresponding starting button has been actuated and this condition stored by a storing relay (not shown).

Relay PC is picked up at the end of the cycle over a circuit previously described, through back contact 17 of relay STR. It is to be noted that field stations can not start a cycle of operations until the system has reached its normal period. This is due to the fact that, even though relay CH¹ drops during a control cycle, it is not effective to pick up relay PL¹, because the circuit through the lower winding of PL¹ is open at some one of the contacts 146, 145, 136 or 135 until the system is in its normal or period of blank condition.

TRANSMISSION OF INDICATIONS

The selection of field stations for outgoing controls followed by the transmission of these controls is accomplished, as above explained, over the single line circuit extending from the control office to the various field stations. The same single circuit is employed, in accordance with this invention, for the transmission of indications to the control office from a station, following the registration of that station having new indications to transmit.

Although this system is of the duplex type, whereby indications may be transmitted from any station to the control office, during the same operating cycle that controls are transmitted to any station from the control office, over the same line circuit, it is convenient to first explain the operation of the system when indications alone are transmitted, during an operating cycle.

There may be trains on various portions of the track in the territory supervised by the operator and these trains may enter or leave track circuits at two or more points in the territory at substantially the same time. Similarly, the switches and signals at the various locations may be operated in such a way, by the operator, that several of these traffic controlling devices may assume new positions at substantially the same time. It will thus be evident that when two or more field stations have new indications to transmit at the same time, it is necessary to prevent more than one field station gaining access to the communication circuit, to avoid mutilation of code calls and the transmission of false indications.

The way in which the field stations are allowed to transmit, one at a time in a predetermined order, is more conveniently explained, following a description of the operation of the system in connection with the transmission of indications from a single field station, assuming that this station is the only one having new indications to transmit at the beginning of the cycle.

Automatic start by a field station.—Referring to Fig. 2, a change in the condition of the detector track section may occur, resulting in track relay T¹ becoming deenergized, assuming this relay to be normally energized as shown in this drawing. Likewise, a change in the condition of other traffic controlling devices may occur, but for the purpose of simplifying this disclosure, such other devices are not shown, but it will be understood that the operation of such other devices results in the momentary deenergization of conductor 152 in the

same manner that this conductor is momentarily deenergized by the release of relay T¹.

The movement of contact 153 of relay T¹ from front to back, or vice versa, momentarily deenergizes the stick circuit of change relay CH¹, allowing this relay to be released. The release of relay CH¹ closes a pick-up circuit for relay PL¹ extending from (+), contact 135 of relay F¹ in the right hand position, back contact 136 of relay VP¹, back contact 145 of relay 3V¹, back contact 146 of relay 1V¹, front contact 154 of relay CHP¹, back contact 155 of relay CH¹ and lower winding of relay PL¹, to (—). Relay PL¹ closes a stick circuit for itself, which is effective during the time that relay SAP¹ is down and which extends from (+), back contact 158 of relay SAP¹, normally closed front contact 159 of relay CHP¹, front contact 160 of relay PL¹ and upper winding of relay PL¹, to (—).

The operation of relay PL¹ opens the line circuit at its back contact 125, which results in the release of relay F¹ at the field station and relay F in the control office. It will be noted that relay F¹ opens the above described pick-up circuit of relay PL¹ at its contact 135. This prevents the picking up of any other relay similar to PL¹, at other field stations at this time and since relay VP¹ will be picked up before relay F¹ is again actuated to its right hand position, the pick-up circuits for relays similar to PL¹ are maintained open at back contacts similar to 136. The pick-up circuits of relays similar to PL¹ are likewise maintained open at back contacts similar to 146 and 145 of relays similar to 1V¹ and 3V¹ respectively, all of which results in preventing any other relay similar to PL¹ being picked up during this operating cycle.

The release of relay F in the control office establishes a circuit for picking up relay STR, extending from (+), back contact 10 of relay SA, back contact 22 of relay F, normally closed front contact 12 of relay FP and winding of relay STR, to (—). Relay STR immediately closes a stick circuit for itself extending from (+), back contact 23 of relay LV, back contacts of all CD relays in series, similar to back contact 24, front contact 16 of relay STR and winding of relay STR, to (—). A branch circuit to (+) is established in multiple with contact 23 of relay LV at back contact 56 of relay PL.

During an operating cycle of this class, no CD relay can be picked up, so that the above described stick circuit for relay STR is maintained until the last "on" period, just before the "change to normal" period. Although the circuit arrangement for preventing the picking up of any CD relay is not shown in Fig. 1, such a circuit may be similar to that disclosed in the above mentioned prior application Ser. No. 455,304.

With relay STR stuck up and since no CD relay can be picked up, no circuit can be established for operating relay PC. A circuit is effective, however, for operating and holding relay NC throughout this cycle, extending from (+), over the above described stick circuit for relay STR and through the front contact 17 of relay STR, to the winding of relay NC. This results in all the impulses in the line circuit being (—) during a cycle of this class.

Referring to the field station circuit, the release of relay F¹, occurring when the line is opened, establishes a circuit for picking up relay PLT¹ extending from (+), contact 135 of relay F¹ in the de-energized position, back contact 162 of relay SA¹ and winding of relay PLT¹, to (—). The

operation of relay PLT^1 closes the line circuit at this station, by way of its front contact 163, upper winding of relay LO^1 , back contact 164 of relay VP^1 , back contact 165 of relay IV^1 and resistance coil R^1 to the upper side of the line. This closure of the line circuit results in picking up relay F^1 at the field station, relay F in the control office and lockout relay LO^1 , since this latter relay is energized through its upper winding by current in the line circuit.

10 This advances the system into the conditioning period, during which control office relays SA^1 , SAP^1 , E^1 , EPT^1 and PL^1 are picked up and relay EP^1 is released, in a manner previously described in connection with the transmission of controls.

15 Referring to the field station, the picking up of relay PLT^1 opens its back contact 166, which is included in the stick circuit of relay CHP^1 , allowing this latter relay to release. Before the 20 release of relay CHP^1 (since it is slightly slow releasing), relay LO^1 establishes a shunt circuit around contact 159 of relay CHP^1 at contact 167 of relay LO^1 . The operation of relay F^1 to the left, since this is a $(-)$ impulse, establishes a 25 circuit for picking up relay FP^1 , extending through its left hand contact 122. The actuation of relay FP^1 closes a substitute circuit, at its front contact 168, for holding relay PLT^1 .

30 Relays SA^1 and SAP^1 are picked up during this period, over circuits described in connection with this same period during transmission of controls. The operation of relay SA^1 completes a stick circuit, through its front contact 169 and front contact 170 of relay LO^1 , for holding relay LO^1 throughout this cycle.

35 A circuit is established for resetting relay CH^1 , before relay SAP^1 is picked up, which extends from $(+)$, back contact 158 of relay SAP^1 , front contact 171 of relay LO^1 , front contact 172 of relay SA^1 and upper winding of relay CH^1 , to $(-)$.

40 The picking up of relay SAP^1 and the opening of its back contact 158, interrupts the stick circuit of relay PL^1 and this latter relay is released, which is effective to close the line circuit through 45 the other stations, by way of back contact 125 of relay PL^1 .

45 This conditioning period is likewise long, since the line is closed until slow releasing relay EP^1 in the control office is dropped. The picking up 50 of relay PL^1 in the control office, as above described, opens the line circuit, which is effective to advance the system into the first "off" period.

55 The operation of the system is now advanced throughout the different "off" and "on" periods, in the same manner previously described in connection with transmission of controls, as far as the stepping relay and half step relay operations are concerned. In this class of call, however, relay STR is maintained in its operated position, as above mentioned, and relay NC remains picked up throughout the cycle for sending a series of $(-)$ impulses.

60 It has been mentioned that relays at other stations, similar to PL^1 of Fig. 2, cannot be picked up to interfere with an indication cycle after it has been initiated by a station, of which that shown in Fig. 2 is typical. Since no other relay similar to PL^1 can be picked up, no other relay similar to LO^1 can be energized, therefore, the code jumper circuits and indication circuits at other stations are not completed during this cycle. During the impulsing of the line circuit, relays similar to F^1 , FP^1 , SA^1 , SAP^1 , PLT^1 and the stepping and half step relays located at other stations

will be actuated in synchronism with corresponding relays shown in Fig. 2.

Registration of a field station.—Since a cycle of operations for the transmission of indications results in operating the stepping and half step relays in a manner previously described in connection with transmission of controls, it is not considered necessary to repeat this description.

One of the features of the present invention 10 resides in means for obtaining double the usual capacity of a centralized traffic controlling system. The following description will be directed to an explanation of the manner in which eight indication code combinations are obtained, in 15 a system such as illustrated in Figs. 1 and 2, in which four control code combinations are obtained. It will be understood that for each control code combination obtained in this system, two indication code combinations are obtainable. 20

It is believed that this feature of the invention may be best understood by assuming that the field station, shown in Fig. 2, is assigned code (short, long "off" periods) and (long, short "on" periods). The above assumption means that the 25 first "off" period is short (normal) and the second "off" period is long (abnormal). The first "on" period is long (normal) while the second "on" period is short (abnormal). This is brought about at the field station by omitting the jumper 30 connection of No. 1 "off" bus 173, which results in the first "off" period being normally short. No. 1 "on" bus conductor 174, likewise has the jumper omitted which results in a normally long first "on" period. No. 2 "off" bus 175 has a jumper 35 190 connection completed to $(+)$, which results in the second "off" period being abnormally long. No. 2 "on" bus 176 has a jumper 193 connection completed to $(+)$, which results in the second "on" period being abnormally short. The 40 No. 3 "on" bus 177 leads to the back contact 178 of relay T^1 , so that the third "on" period will record, in the control office, the position of relay T^1 , after this station has been registered in the 45 control office.

Other indication buses, leading to bracket IB , may be connected or disconnected from $(+)$ potential in a similar manner for obtaining additional indications. It is believed however, that an example sufficient for the understanding of 50 this operation is given in connection with the above enumerated "off" and "on" periods.

From the above it will be seen that a de-energized "off" bus results in a short "off" period, while an energized "off" bus results in a long "off" 55 period. A de-energized "on" bus results in a long "on" period, while an energized "on" bus results in a short "on" period.

Assuming that synchronous stepping occurs in the control office (Fig. 1) and at the field station 60 (Fig. 2), reference will be made to the above table and an explanation will be given how the combination of short and long "off" and "on" periods are obtained, together with the conditioning of the pilot relays in the control office, 65 for selectively registering the desired station.

The first "off" period which follows the conditioning period is assumed to be short. This is because the jumper connection (Fig. 2) between bus 173 and $(+)$ is omitted. Relay CHP^1 is 70 down during a cycle of this class so that the only circuit for picking up the line pulsing relay PL^1 is by way of its upper winding. During the "off" periods the circuit of relay PLT^1 is interrupted at front contact 168 of relay FP^1 , but a sus- 75

taining circuit is completed to energize relay PL^1 , extending from (+), front contact 158 of relay SAP^1 , back contact 179 of relay PL^1 and winding of relay PL^1 , to (-).

5 A circuit may be traced from the No. 1 "off" bus 173, back contact 181 of relay $2V^1$, front contact 182 of relay VP^1 , front contact 183 of relay LO^1 , back contact 184 of relay FP^1 , front contact 185 of relay PL^1 and upper winding of relay PL^1 , to (-). Since the jumper connection of bus 173 is omitted, the above traced circuit is not effective to energize relay PL^1 , so that the line circuit is not opened at the station under this condition.

15 Inasmuch as the line circuit is not opened at the station, it is energized at the control office by the release of relay PL , which follows the release of relay E and the picking up of relay EP . Relay PL closes the line at its back contact 28. This 20 results in a short or normal first "off" period.

25 The system advances from the first "off" period to the first "on" period in a comparatively short interval of time, and the No. 1 "off" indication, which was conditioned (short) during the first 30 "off" period, will be executed in the first "on" period. Relay EPT in the control office is not released when the "off" indication is short, because the system advances into the "on" period and picks up relay F , before relay EPT has time to drop its armature, thus establishing a holding stick circuit for relay EPT through its front contact 35 39.

35 In the first "on" period, the No. 1 short "off" indication, above described, is executed by extending a circuit from (B-), front contact 72 of relay EPT , front contact 73 of relay F , back contact 74 of relay E , front contact 75 of relay VP , back contact 76 of relay $2V$, No. 1 "off" indication bus 77 and winding of relay $1PF$, to (CN). 40 Current through polar magnetic stick relay $1PF$ is in such a direction that it will be positioned to the left, as shown in Fig. 1.

45 During the first "on" period, the No. 1 "on" indication is conditioned by a circuit extending from bus 174, through front contact 186 of relay $1V^1$, back contact 187 of relay $3V^1$, front contact 188 of relay VP^1 , front contact 189 of relay LO^1 , front contact 184 of relay FP^1 , front contact 185 of relay PL^1 and upper winding of relay PL^1 , to (-). But since bus 174 is not connected to (+), relay PL^1 is not picked up. The line is therefore, not opened at the field station during this period, so that it remains closed for a long interval, marked off by the release of relay EP in the control office, which picks up relay PL and opens the line at its back contact 28.

50 The system next advances into the second "off" period, where "on" indication No. 1, above described, is executed. The "on" indication No. 1 is long and since relay EP is down, a circuit is closed for executing this long indication, extending from (B-), back contact 78 of relay EP , back contact 79 of relay F , front contact 57 of relay E , back contact 80 of relay LV , back contact 81 of relay $3V$, back contact 82 of relay $2V$, front contact 83 of relay $1V$, No. 1 "on" indication bus 84 and winding of relay $1PB$, to (CN). Current in this circuit is in a direction to position relay $1PB$ to the left as shown.

55 During this, the second "off" period, "off" indication No. 2 is conditioned, by means of a circuit extending from (+), jumper 190, No. 2 "off" bus 175, front contact 191 of relay $1V^1$, back contact 192 of relay $3V^1$, back contact 182 of relay VP^1 , front contact 183 of relay LO^1 , back contact 184

of relay FP^1 , front contact 185 of relay PL^1 , and upper winding of relay PL^1 , to (-).

Due to this completed circuit, relay PL^1 will be picked up which results in opening the line at the field station, at back contact 125. Since relay $1V^1$ is up, the line circuit is open at its back contact 165. The control office attempts to energize the line, in the manner above described for the first "off" period, by dropping relay PL in a comparatively short time. The field station, however, maintains the line open at contact 125 of relay PL^1 and this relay opens the circuit of relay PL^1 , at back contact 179. Relay PL^1 releases, after a comparatively long interval, and opens the above traced circuit through the upper winding of relay PL^1 , at contact 185. Relay PL^1 drops and energizes the line circuit.

This extends the second "off" period, making it abnormally long. When the line is finally energized by relay PL^1 at the field station dropping and closing its back contact 125, the system is advanced into the second "on" period, where the No. 2 "off" indication is executed. After relay E was dropped, during the second "off" period, relay F was not again picked up in time to complete the sustaining stick circuit for relay EPT through its front contact 39. This allows relay EPT to release, completing the circuit for executing the No. 2 "off" indication (long), extending from (B+), back contact 72 of relay EPT , front contact 73 of relay F , back contact 74 of relay E , back contact 75 of relay VP , back contact 85 of relay $3V$, front contact 86 of relay $1V$, No. 2 "off" indication bus 87 and winding of relay $2PF$, to (CN). Current in this circuit is in such a direction that relay $2PF$ will be positioned to the right as shown in Fig. 1.

55 During the second "on" period, the No. 2 "on" indication is conditioned. Code jumper 193 is connected to (+) and a circuit is completed from this code jumper, by way of No. 2 "on" indication bus 176, front contact 194 of relay $2V^1$, back contact 195 of relay $3V^1$, back contact 188 of relay VP^1 , front contact 189 of relay LO^1 , front contact 184 of relay FP^1 , front contact 185 of relay PL^1 and upper winding of relay PL^1 , to (-).

60 Relay PL^1 is picked up and held until the release of relay PL^1 which occurs in a comparatively long interval of time, after its circuit is opened at back contact 179 of relay PL^1 . The picking up of relay PL^1 opens the line circuit at the field station, before it would otherwise be opened in the control office, by the dropping of slow relay EP . This results in reducing an otherwise normally long "on" period to an abnormally short "on" period.

65 Opening the line circuit advances the system into the third "off" period, where the short No. 2 "on" indication is executed. Relay EP did not have time to drop during the second "on" period and the system advances into the third "off" period with relay EP up. The release of relay F closes a circuit for executing the No. 2 "on" indication, extending from (B+), front contact 78 of relay EP , back contact 79 of relay F , front contact 57 of relay E , back contact 80 of relay LV , back contact 81 of relay $3V$, front contact 82 of relay $2V$, No. 2 "on" indication bus 88, and winding of relay $2PB$, to (CN). The current in this circuit is in such a direction that relay $2PB$ will be positioned to the right, as shown in Fig. 1. Relay E drops during this, the third "off" period and closes a circuit for energizing relay EP , before this latter relay has time to release.

Examples have been given of the conditioning and executing circuits for short and long "off" and "on" periods. It is believed that these examples are sufficient to show how these "off" and "on" periods may be varied in order to obtain other code combinations. It is obvious that No. 1 "off" indication bus 173, if connected to (+) by a jumper, would result in a long first "off" period. Under this assumption, relay 1PF 10 in Fig. 1 would be positioned to the right, because relay EPT would be dropped to apply (B+) to the No. 1 "off" indication bus 17.

It should be understood that additional pilot relays, similar to 1PF, 1PB, etc., may be provided and positioned on any desired number of steps, but for the sake of simplicity, only two have been shown operated during the "off" periods and two operated during the "on" periods.

It will be obvious that with two steps, sixteen different code combinations or selections through the station registering pilot relays may be made. It will be understood, however, that the sixteenth or last combination, composed of all normal periods, that is, short "off" periods and long "on" periods throughout a cycle of operations, cannot be used for station registration for indications, since this is the inherent combination obtained during the transmission of controls alone, which must result in the failure of the system to register any station for inbound calls.

Transmission of indications.—After having registered the particular station in the control office, which has indications ready to transmit, the remaining steps of the cycle are employed for the transmission of such indications.

For example, the No. 3 "on" indication bus 177 is shown connected to a normally open back contact 178 of relay T¹. During the third "on" period, bus 177 is extended by way of front contact 187 of relay 3V¹, front contact 188 of relay VP¹, front contact 189 of relay LO¹, front contact 184 of relay FP¹, front contact 185 of relay PLT¹ and upper winding of relay PL¹, to (—). If the track relay T¹ is in the position shown in Fig. 2, this circuit is ineffective to energize relay PL¹, with the result that this third "on" period will be normally long, for the reason described above in connection with the first "on" period.

Therefore, relay EP in Fig. 1 will be down during the fourth "off" period when the No. 3 "on" indication is executed. This completes a circuit from (B—), through back contact 78 of relay EP, back contact 79 of relay F, front contact 57 of relay E, back contact 80 of relay LV, front contact 81 of relay 3V, No. 3 "on" indication bus 88, contacts 90, 91, 92 and 93 of the pilot relays, positioned as above described, and winding of indication relay IRF, to (CN). Current over this circuit results in positioning relay IRF to the left for displaying indication lamp I.

If track relay T¹ is down when this indication is conditioned, the circuit completed through its back contact 178, during the third "on" period, is effective to pick up relay PL¹, over a circuit which has previously been traced. Relay PL¹ opens the line at the field station, before waiting for relay EP in the control office to drop and pick up relay PL for opening the line, so that a short No. 3 "on" indication is conditioned during the third "on" period.

During the fourth "off" period, since relay EP did not drop, a circuit is extended from (B+), front contact 78 of relay EP and the remainder 75 of the circuit previously described, through con-

tacts of the pilot relays, resulting in positioning relay IRF to the right.

It will now be obvious how additional indication buses, IB of Fig. 2, may be variably connected for variably selecting additional pilot or 5 indication relays, similar to 1PB, 1PF, 1RF, etc., in the control office.

End of indication cycle.—The step-by-step operations and the impulsing of the line circuit during an indication cycle are similar to those 10 operations during a control cycle and the line is opened, following the last impulse or "on" period, in a manner similar to that previously explained, which allows the relays to assume normal positions. The release of relay SA in the 15 control office opens the pick-up circuit of relay SAP and at the same time establishes a stick circuit for relay FP, for holding this latter relay in its operated position until after the start of 20 the next cycle.

The release of relay SA¹ at the field station opens the circuits of relays LO¹ and SAP¹ and they are dropped. The release of relay SAP¹ at the field station opens the stick circuit of the stepping relays and the half step relay and they 25 are restored to normal.

It has been explained that relay CH¹ is picked up during the conditioning period. As soon as the system is advanced into its normal period, a circuit for picking up relay CHP¹ is effective, 30 extending from (+), contact 135 of relay F¹ in the right hand position, back contact 136 of relay VP¹, back contact 145 of relay 3V¹, back contact 146 of relay 1V¹ and lower winding of relay CHP¹, to (—). Relay CHP¹ is again stuck 35 up through back contact 166 of relay PLT¹ until after the start of the next cycle.

Lock-out between field stations.—As previously mentioned, it may happen that changes take place at several field stations simultaneously or in 40 rapid succession, so that more than one field station will have new indications to transmit at the beginning of a cycle. In order to prevent more than one field station obtaining access to the line during any cycle of operations, lock-out 45 means are provided at each field station effective to give control of the line to the field station nearest the control office, under the above conditions.

It has already been explained that the instant 50 a relay similar to F¹ at a field station is dropped, during the initiating and lock-up period, no other relay similar to PL¹ at any field station can be picked up. The only PL¹ relay up will be the one which initiates a cycle of operations for the transmission of indications. This is, of course, assuming that other stations attempt to seize the line shortly after the line has been taken by a single station for sending in new indications.

It may occur, however, that relays similar to 60 CH¹ may be down at the same time, while the system is in its normal or period of blank condition. In this case, two or more relays similar to PL¹ can be picked up, over circuits similar to those previously described for picking up relay PL¹ of 65 Fig. 2.

It is believed that the lock-out feature may be best understood by assuming that two relays similar to PL¹ are picked up at the same time and explaining how only the station nearest the control office is effective to transmit indications over the line circuit under this condition. It will be understood that the operation is the same when more than two relays, similar to PL¹ are picked up, since only the station nearest the control 75

office in this instance will be effective to transmit indications.

The two relays similar to PL^1 which are assumed picked up will be stuck up over circuits similar to 5 that extending from (+), back contact 158 of relay SAP^1 , front contact 159 of relay CHP^1 , front contact 160 of relay PL^1 and upper winding of relay PL^1 , to (-).

When relays similar to F^1 at these two stations are dropped, the two relays similar to PLT^1 are picked up, over circuits similar to those previously described in connection with Fig. 2. The picking up of the relay similar to PLT^1 , at the station nearest the control office, closes the circuit of the line through the upper winding of the lock-out relay similar to LO^1 at this station. At the same time, the relays similar to PLT^1 at both stations, open the stick circuits of relays similar to CHP^1 at both stations allowing these two 20 relays to drop away. They are slightly slow to release so that the lock-out relay similar to LO^1 at the station nearest the control office, has time to be picked up and establish a sustaining stick circuit for the relay similar to 25 PL^1 , at a front contact similar to 167, before this stick circuit is broken by the opening of a back contact similar to 159 of the relay similar to CHP^1 .

The lock-out relay similar to LO^1 at the farther station, does not get current, therefore, when the relay similar to CHP^1 , at the farther station drops its armature, there is no circuit for holding the relay similar to PL^1 at the farther station and it is released, which is effective to complete the 35 closure of the line circuit through the other stations.

Current over the line circuit is (-), flows through the station nearest the control office and causes relays similar to F^1 , FP^1 , SA^1 and SAP^1 40 at this station to be picked up. Since the relay similar to PLT^1 was picked up at the time the line was opened, the circuit at this nearest station is closed through front contact 163 of this relay and the upper winding of the lock-out relay similar 45 to LO^1 . The relay similar to SA^1 establishes a stick circuit to hold the lock-out relay at its front contact, similar to 169 and this circuit is maintained throughout the operating cycle.

When the relay similar to SAP^1 , at the station 50 nearest the control office picks up, the relay similar to PL^1 is dropped, because its stick circuit is interrupted at a back contact similar to 158. It will be recalled that after the relay similar to F^1 leaves its right hand contact, no relay similar to 55 PL^1 can be picked up through its lower winding.

It will now be evident that the station nearest the control office is the only one with its relay similar to LO^1 picked up, so that this is the only station where the indication buses are connected 60 through front contacts similar to 183 and 189 of the lock-out relay. This is the only station effective to transmit indications to the control office by impulsing the line circuit.

The relay similar to CH^1 at the station nearest 65 the office, is again picked up when the relay similar to SA^1 is picked up, over a circuit which has been previously described, including a front contact of the lock-out relay. It will thus be seen that other relays similar to relay CH^1 , will remain down at those other stations having new indications to transmit, until they each get a chance to obtain access to the line. Since the relay similar to CH^1 at the station nearest the control office is picked up at the beginning of the 70 cycle, it may thereafter be again released for a

subsequent seizure of the line circuit, if additional new indications are to be transmitted from this station, at the start of the next operating cycle.

From the above it will be understood that, irrespective of whether the new indications to be transmitted occur simultaneously or sequentially, the field station nearest the control office will be the only one which obtains current for energizing its lock-out relay and for impulsing the line. Those stations farther away from the control 10 office will not have their lock-out relays picked up, their relays similar to PL^1 will not be picked up, which results in the line circuit being conductively completed through back contacts similar to 125, of relays similar to PL^1 at those other 15 stations.

An important feature of the present invention relates to the organization of the circuits in a two-wire lock-out system to maintain synchronous stepping at all stations during a cycle, at the start of which there are a plurality of stored field and office start conditions. This is necessary in a duplex system in order that controls may be properly transmitted during the same cycle that the lock-out feature has been effected. 20 25

From the above description relating to the lock-out feature, it will be noted that the line circuit is maintained closed up to the station which obtains access to the line and is opened to stations beyond this point. It therefore, becomes necessary to so arrange the circuits that the two different conditions of the line (open and closed) at the different stations do not result in causing the stepping and other operations at these different stations to get out of synchronism. 30 35

Under the above conditions, current of (-) polarity flows to the field station nearest the office during the conditioning period and picks up relays F^1 , FP^1 , SA^1 and SAP^1 as above described. 40 Corresponding relays are picked up at other stations toward the control office but at stations farther out along the line these corresponding relays do not pick up (due to the line circuit being opened at back contact 125 of relay PL^1) until 45 relay PL^1 drops.

When relay PL^1 is released (by the picking up of relay SAP^1), the continuity of the line is transferred from the path through the winding of relay LO^1 to the path through the line circuit extending through the other stations farther out 50 the line. Relays corresponding to relays F^1 , FP^1 , SA^1 and SAP^1 at those other stations are now picked up by this conditioning (-) impulse and the cycle is carried through with all stations 55 working in synchronism. Since relay VP^1 picks up during the first "off" period and since relay IV^1 is picked up before relay VP^1 drops, the impulsing of relay PL^1 is effective to open the line which extends through all stations at back 60 contact 125. This is done without closing the line through the winding of the lock-out relay because this branch of the circuit will be maintained open at contact 164 of relay VP^1 or contact 65 165 of relay IV^1 .

Two-way transmission.—It has been pointed out that control and indication cycles may each occur separately or simultaneously. The operation for each of these cycles alone has been described in detail and it will now be explained 70 how the system operates when controls and indications are transmitted during the same cycle.

The actuation of a starting button in the control office and the picking up of relay CD which follows, results in picking up the start relay STR , 75

during the time the system is at normal and during the time up to the pick-up of relay SA, during the conditioning period. After the pick-up of relay SA, the circuit for picking up the start relay STR is interrupted at back contact 10 of relay SA, if a field station has initiated the cycle.

10 The actuation of a starting button in the control office and the picking up of its corresponding CD relay results in picking up relay STR and sticking it until the first "off" period, when it is dropped, as has been described in connection with the transmission of controls alone.

15 For the transmission of indications alone, relay STR is picked up and stuck up until the end of the cycle, over a series stick circuit, extending through back contacts of all CD relays. This has been described in connection with the transmission of indications alone.

20 For a duplex cycle, when controls and indications are both transmitted during the same cycle, relay STR will be picked up by means of the previously described circuit, through front contact 11 of a CD relay, or back contact 22 of relay

25 F. Relay STR will be dropped during the first "off" period in this case, because some CD relay will be up to open the series stick circuit above described.

30 At the start of a duplex cycle, station relays PL¹, PLT¹ and LO¹ are picked up, relay CHP¹ is dropped and relay LO¹ is stuck up until the end of the cycle, all of which has been described in connection with the transmission of indications alone. The lockout feature is likewise effected

35 in the same manner as described for the transmission of indications alone.

40 During a duplex cycle, the impulse applied to the line circuit, during the conditioning period, is (—) and the following impulses are (+) or (—), determined by the particular CD relay in the control office which is up. The "off" periods are short (normal) or long (abnormal) and the "on" periods are long (normal) or short (abnormal), as determined by code buses selected by a lockout relay, similar to LO¹, which is up at a particular field station.

45 It is therefore, evident that since only one CD relay in the office and one lockout relay at a field station can be up at one time, during a cycle of operations and since transmission of controls and transmission of indications take place during separate and distinct conditions of the line, these transmissions are independent of each other and 50 can be incorporated into the same operating cycle for obtaining the duplex feature.

55 The resulting cycle of operations, insofar as the transmission of impulses over the line circuit, the application of the short and long "off" and "on" periods and the conditioning and executing circuits are concerned, are the same as described for separate control and indication cycles.

60 In a system of this character where stepping impulses are applied to the line circuit for the transmission of indications alone, it will be evident that some means must be provided to prevent such impulses from being effective to control or govern the selection or transmission of controls to any field station.

65 Similarly, when the system is transmitting controls alone, some means must be provided to prevent the normal "off" and "on" periods from being effective to register indications in the control office from any field station, so that a

cycle of this class will not cause any operation of the indication devices.

70 In the system of the present invention, when the system is transmitting controls alone and the "off" and "on" periods are of normal duration throughout the cycle of operations, such a code, which would correspond to all "off" periods being short and all "on" periods being long, does not register any field station in the control office. This may be termed a code call for a phantom station.

75 Similarly, when indications are being transmitted alone during an operating cycle, all of the impulses in the line circuit are (—) and that code call corresponding to all (—) impulses is not employed for the selection of any field station. This combination of (—) impulses may be termed a code call for a phantom station.

SUMMARY

20

The present embodiment has been described, more particularly with reference to the character of the devices employed in a centralized traffic controlling system and their respective functions, together with typical operating conditions and it will be understood that all possible combinations of circumstances can not be considered in detail.

The system may be initiated into a cycle of operations from a normal condition, by a change in condition either at the control office or at any one or more of the field stations. Such change in condition causes the system to go through an operating cycle, comprising an initiating and lockout period, a conditioning period, a transmitting portion of the cycle, referred to as the "off" and "on" periods and the "change to normal" period at the end of the cycle.

50 During the initiating and lockout period, the various relays are positioned and the system is started through a cycle. Changes may occur at any time during this period but at the time the line relays, similar to F¹ at the field stations, are released and from this point on during the cycle, changes at any field station are ineffective to govern the character of the cycle. Likewise, after the picking up of any CD relay in the control office, the following cycle of operations determines the character of such cycle to be for the transmission of controls. Indications may be 55 transmitted along with controls during this cycle if a lockout relay is up at the start of the cycle.

A cycle of operations, therefore, may be for the transmission of controls and/or the transmission of indications. The controls are transmitted by (+) and (—) impulses applied to the line circuit, while the indications are transmitted by varying the time intervals during which the line circuit is energized and de-energized.

The lockout period is marked off by the dropping of relays similar to F¹ at the field stations and in the event that two or more stations are ready to transmit new indications at the start of an operating cycle, only one station is effective to obtain control of the line circuit, since 60 only one lockout relay can be up at any one time.

The present system also discloses means whereby each field station lockout relay is restored to normal at the end of a cycle, so that all field stations will be synchronized at the beginning 65 of each cycle.

70 Following the initiating and lockout period, the conditioning period is effective to condition the cycle demarcating relays SA, SA¹, SAP and SAP¹ in the control office and at the field sta- 75

tions, as well as conditioning the line impulsing relay for starting the series of impulses.

The transmitting part of the cycle follows, during which each successive impulse applied 5 to the line circuit results in the energization of a three-position polar magnetic stick type relay at each field station for effecting the selection of a particular station and for receiving controls. The stepping relays at the control 10 office and at the several stations take their steps during the "on" periods, when the line is energized. The half step relays at the control office and at the several field stations are shifted during the "off" periods, when the line is de-energized. During the odd "off" periods, these half 15 step relays are picked up and during the even "off" periods, they are dropped.

For the transmission of indications, the line circuit is either energized for a normally long 20 period or an abnormally short period and is de-energized for a normally short period or an abnormally long period, to position message receiving relays in the control office. These message receiving relays are indicated in Fig. 1 as 25 EPT, for receiving the messages during the "off" periods and EP, for receiving the messages during the "on" periods. The relay (EPT) which receives the messages during the "off" periods, executes these messages during the next succeeding "on" periods. The relay (EP) which receives the messages during the "on" periods, executes these messages during the next succeeding 30 "off" periods.

In other words, indications are conditioned 35 twice for each step, once during the "off" periods and once during the "on" periods. These two conditions are made effective, when they are executed, to position two-position polar magnetic stick type relays, indicated 1PF, 2PF, 1PB and 40 2PB in Fig. 1. Thus, the stations and indications are registered in the control office over a single line circuit, which is also used for transmission of controls and these indications are transmitted twice as fast as the controls. Such a system 45 not only renders the most efficient use of the transmission line, but it is particularly adaptable to centralized traffic controlling operations, since a larger number of indications than controls are usually required for the proper supervision 50 in such a system.

At the end of the transmitting part of the cycle, the line circuit is maintained open in the control office for a prolonged period of time, until the slow acting relays SA and SAP are 55 de-energized, which provides sufficient time for restoring the relays to normal at the control office and at all of the field stations.

Various other novel features of the present 60 invention reside in the circuit arrangements disclosed, such as the transmission of controls during the "on" periods by conditioning the polarity selecting relays in the control office, by way of contacts on stepping relays which do not shift when the control is transmitted. In 65 other words, the polarity of a control impulse is selected during an "off" period and is maintained during the subsequent "on" period, notwithstanding the fact that a stepping relay is picked up during the subsequent "on" period.

70 Although one specific embodiment of the invention has been shown, it is to be understood that various rearrangements of the circuits may be made without departing from the spirit of the invention. For example, the familiar SO 75 relay arrangement, disclosed in the above men-

tioned prior application, Ser. No. 455,304, for dropping out all field stations except the one desired during transmission of controls, could be used instead of the station relays 1ST¹, 2ST¹ and 3ST¹ of Fig. 2.

Having thus described one specific embodiment of a centralized traffic controlling system, it is desired to be understood that this particular form has been selected to facilitate in the disclosure of the invention, rather than to limit it and it is to be further understood that various modifications, adaptations and alterations may be applied to the specific form disclosed, without in any manner departing from the spirit or scope of the present invention, except as 15 limited by the appended claims.

What we claim is:

1. In a centralized traffic controlling system, a control office, a field station, a line circuit connecting said control office with said field station, step-by-step mechanisms at said control office and at said field station, means for operating said mechanisms in synchronism by energizing said line circuit with a series of impulses, means at said control office for controlling said line circuit to provide a normally long impulse, means at said field station for controlling said line circuit to provide an abnormally short impulse, and means responsive to a combination of said long and short impulses during 20 the operation of said mechanisms for registering said field station in said control office. 25

2. In a centralized traffic controlling system, a control office, a field station, a line circuit connecting said control office with said field station, step by step mechanisms at said control office and at said field station, means for operating said mechanisms in synchronism by a series of impulses applied to said line circuit, means at said control office for controlling said line circuit to provide a normally long impulse and a normally short time interval between impulses, means at said field station for reducing the length of said long impulse and for extending the length of said short time interval 35 to form a code combination, and means controlled by said code combination for registering said field station in said control office during 40 the operation of said mechanisms. 45

3. In a centralized traffic controlling system, a control office, a field station, a normally energized line circuit extending from said control office to said field station, means at said control office for de-energizing and energizing said line circuit to form a series of equally time-spaced 50 impulses of equal duration, step by step mechanisms at said control office and at said field station operated in synchronism by said impulses, code selecting means at said field station operable successively by said mechanism to change 55 said impulses to a series of unequal time spaced impulses of unequal duration, and means at said control office for registering said unequal time spacings and impulses during the operation of said mechanisms. 65

4. In a centralized traffic controlling system, a control office, a plurality of field stations, a line circuit connecting said control office with said field stations, step-by-step mechanism at said control office and at said field stations, means 70 for energizing said line circuit with a series of impulses of distinctive character, means responsive to said impulses for operating said step-by-step mechanisms in synchronism, means for varying the lengths of said impulses during the oper- 75

ation of said mechanisms, means responsive to the character of said impulses for selecting one of said field stations during the operation of said mechanisms, and means responsive to the lengths 5 of said impulses for registering another of said field stations in said control office during the operation of said mechanisms.

5. In a centralized traffic controlling system, a control office, a plurality of field stations, a line 10 circuit connecting said control office with said field stations, step-by-step mechanism at said control office and at said field stations, means for energizing said line circuit with a series of time spaced impulses of distinctive character, means 15 responsive to said impulses for operating said step-by-step mechanisms in synchronism, means for varying the lengths of said impulses and the time spaces between the impulses during the operation of said mechanisms, means responsive to the character of said impulses for selecting one 20 of said stations during the operation of said mechanisms, and means responsive to the variations in time between and the lengths of said impulses for registering another of said stations 25 in said control office during the operation of said mechanisms.

6. A selector system for transmitting messages from a central office to a plurality of field stations, in which a line circuit is energized by a 30 series of characteristic impulses applied thereto, odd and even stepping relays, circuit means controlled by said impulses for alternately actuating odd and even stepping relays in succession, each odd relay being actuated during an odd impulse 35 and each even relay being actuated during an even impulse, a circuit including contacts of said odd stepping relays and exclusive of contacts of said even stepping relays, and means including said circuit for selecting the character of said 40 even impulses.

7. In a centralized traffic controlling system, a control office, a plurality of field stations, a line circuit connecting said control office with said field stations, step-by-step mechanism at said 45 control office and at said field stations, signalling devices at said field stations and indicating devices at said control office, means at said control office for applying a plurality of time spaced impulses of distinctive character to said line circuit for effecting an operating cycle of said mechanisms, means at each of said field stations for varying the time spaces between said impulses and for varying the lengths of said impulses, means at each of said field stations responsive to 55 the character of said impulses for selecting the associated field station and for operating the signalling devices therat during an operating cycle of said mechanisms, and means at said control office responsive to the variations in time between 60 and the lengths of said impulses for registering a selected field station in said control office and for operating its associated indicating devices during said operating cycle.

8. In a centralized traffic controlling system, a 65 control office, a field station, a line circuit connecting said control office with said field station, step-by-step mechanisms at said control office and at said field station, means for operating said mechanisms in synchronism by energizing 70 said line circuit with a series of impulses, means at said control office for controlling said line circuit to provide normally long impulses, means at said field station for transmitting code messages to said control office by controlling said 75 line circuit to change said normally long impulses

to abnormally short impulses, an impulse registering relay, means responsive to the length of said impulses for distinctively operating said impulse registering relay during the operation of said mechanisms, and means responsive to the 5 distinct operation of said impulse registering relay for registering said code messages in said control office.

9. In a remote control system, an office and a station, a line wire connecting the office and station, stepping apparatus for transmitting a series of time-spaced impulses of current one at a time in sequence from the office to the station over said line wire, a series of movable devices at the station, a series of indicators at the office including one for each device, means at the station for selectively controlling the length of each impulse and of each interval between impulses of said series, means at the office for selectively controlling the relative polarity of each of said impulses, means for controlling said devices each in accordance with the relative polarity of a selected impulse of said series, means for controlling certain of said indicators of said series each in accordance with the relative length of a selected impulse of said series, and means for controlling the remaining indicators of said series each in accordance with the relative length of a selected interval between impulses of said series. 15 20 25

10. In a remote control system, two stations 30 connected by a single line circuit, a series of movable devices at each station, means for transmitting over said line circuit a series of time-spaced impulses of current, comprising means at one station for selectively controlling the 35 length of the impulses and of the intervals between impulses, and means at the other station for selectively controlling the relative polarity of the impulses, means for controlling a selected device at one station to one position or another in 40 accordance with the relative length of a particular impulse of the series, means for controlling another selected device at said station to one position or another in accordance with the relative length of the interval between said impulse 45 and the next impulse of the series, and means for controlling a selected device at the other station to one position or another in accordance with the relative polarity of said impulse. 50 55

11. In a remote control system, two stations 50 connected by a single line circuit, a series of movable devices at each station, means for transmitting over said line circuit a series of time-spaced impulses of current, comprising means at one station effective to selectively control the 55 length of each impulse of said series, and means at the other station effective to selectively control the relative polarity of each impulse of said series; means effective to control the devices at said one station each in accordance with the relative polarity of a particular impulse of said series, and means effective to control the devices at said other station each in accordance with the relative length of a particular impulse of said series. 60 65

12. In a remote control system, a receiver comprising a line relay adapted to be energized repeatedly by consecutive elements of a series of timed impulses of current, a slow release relay adapted to become released if the line relay remains energized for more than a predetermined 70 time interval, a series of polarized indication relays, one for each element, and means rendered effective each time the line relay becomes de-energized for energizing a selected one of said indication relays to one position provided said 75

slow release relay is then energized and to another position provided said slow release relay is then deenergized.

13. In a remote control system, a receiver comprising a two-position line relay adapted to be actuated repeatedly by consecutive elements of a series of impulses of current, of variable duration and variable time spaces between such impulses, a pair of slow release relays, means for energizing one slow release relay only when the line relay is in one position and for energizing the other slow release relay only when the line relay is in the other position, a series of indication relays, and means effective each time the line relay moves from either position to the other position to momentarily energize a selected one of said indication relays to one position or another in accordance with the position occupied at that time by the slow release relay which then becomes energized.

14. In combination, a two-position relay, means for operating said relay alternately to said two positions for selected time intervals, two timing devices one arranged to commence its operation when the relay is moved to said one position and the other arranged to commence its operation when the relay is moved to the other said position, a series of two position indicators, stepping apparatus effective to render said indicators available for operation in accordance with the condition of said timing devices one at a time in sequence as said relay is operated repeatedly, whereby each of said indicators may be operated to one position when said relay is operated provided the last-operated timing device has completed its operation and to the other position provided said timing device has not completed its operation.

15. In combination, a normally closed circuit including a line wire connecting an office and a station, a series of movable devices at the station, means operating in response to a change in condition of any one of said movable devices for opening said circuit, means responsive to the opening of said circuit for rendering one of said movable devices effective to determine the closing of said circuit, means responsive to such closing of said circuit to render the next succeeding movable device of the series effective to again open said circuit, means at the office for supplying current of a selected polarity to said circuit, means for selectively controlling the condition of one of said devices in accordance with the polarity of said current, an indicator at the office for each device, and means selectively responsive to the length of time said circuit is opened and closed under the control of said movable devices for controlling the corresponding indicators.

16. A centralized traffic control system comprising, a single line circuit connecting a control office and a field station, means in the control office for determining the polarity of successive energization of said line circuit, the polarity of each of said energizations being selected in accordance with the controls to be transmitted from the control office to the field station, step-by-step means at the field station operating to close contacts sequentially in response to the successive energizations of said line circuit, means governed by said contacts for controlling the continuity of said line circuit for each energization thereof to vary the time duration of such energization in accordance with the indications to be transmitted from the field station

to the control office, and indicating means in the control office responsive distinctively to the different durations of each energization.

17. In a centralized traffic control system, the combination with a single line circuit intermittently energized with current impulses of a variable time duration, stepping relays energized sequentially one at a time for each energization of said line circuit, a plurality of polar indication relays one for each stepping relay, said indication relays having contacts which remain where set by an energization until changed by a subsequent energization of the opposite polarity, an energizing circuit for each of said indication relays including a front contact of a particular stepping relay, timing means conditioned distinctively in accordance with the duration of energization of said line circuit for determining the polarity of energization of the circuits for said indication relays, and means for momentarily closing said indication relay circuits upon each deenergization of said line circuit and thereby causing energization of the corresponding indication relay with a polarity determined by the then existing condition of said timing means.

18. In a centralized traffic control system of the synchronous code type, a single line circuit extending between a control office and a field station, step-by-step means in the control office and at the field station operated synchronously by impulses applied to said line circuit, a source of current in the control office, manually controllable means governed also by said step-by-step means in the control office for controlling the connections between said source of current and said line circuit to determine the polarity of the successive energizations of said line circuit, traffic controlling means at the field station governed in accordance with the polarity of said successive energizations, devices at the field station having variable conditions to be indicated in the control office, means at the field station governed by said devices and by the step-by-step means for determining the time duration of both the energization and deenergization of said line circuit, and indicating means in the control office responsive to the duration of the successive energizations and deenergizations of said line circuit and thereby manifesting the condition of said devices at the field station.

19. In a remote control system, a control office and a plurality of field stations, a single line circuit extending from said control office through said field stations, a source of energy at said control office, means at said control office including said source of energy for applying a series of uniformly timed spaced impulses of uniform duration to said line circuit, transmitting means at each of said field stations effective during a selected series of impulses for opening and closing said line circuit to lengthen certain of said time spaces and shorten certain of said impulses of that series in accordance with the station code call and the indications to be transmitted from that station, receiving means at said control office distinctively responsive to the lengthened time spaces and shortened impulses of any series to register the particular field station transmitting during that series and the indications transmitted from such field station, and means effective to allow only a selected one of said field stations to transmit by opening and closing said line circuit during any one series of impulses applied to said line circuit at said control office.

20. In a remote control system; a control of-

fice and a plurality of field stations; a line circuit extending from said control office through said field stations; code transmitting means at said control office for energizing said line circuit with different series of time spaced impulses of distinctive characters, the characters of the impulses for any series being selected in accordance with a code call assigned to one of the field stations and the controls for that station; code 5 receiving means at each of said field stations rendered effective in response to that particular series of impulses having its distinctive characters selected in accordance with its code call to receive the controls for that field station; indication transmitting means at each of said field 10 stations capable of varying the length of said impulses and the time spaces between said impulses of any series of impulses when rendered effective to distinctively condition said line circuit for each impulse and for each time space 15 in accordance with the code call and indications of that station; means at the control office responsive to the distinctive conditions of said line circuit during any series of impulses for registering 20 that one of said stations transmitting during such series and for storing its indications; and means for rendering effective the indication transmitting means at only one station during any one particular series of impulses applied to 25 said line circuit at the control office.

21. In a selector system for transmitting messages from a central office to a field station in which a line circuit is energized by a series of time spaced distinctive impulses applied thereto, line relay means for repeating said impulses and 30 time spaces, a series of stepping relays, a single half-step relay, circuit means controlled by said line relay means and said half-step relay for energizing said stepping relays successively in synchronism with said impulses one during each 35 impulse, circuit means controlled by said line relay means and said stepping relays for positioning said half-step relay to an opposite position during each successive time space, storing 40 means for storing the distinctive characters of said impulses, and circuit means controlled by said line relay means for energizing said storing means in accordance with the character of each 45 impulse of said series, said circuit means for a given impulse including a front contact of a stepping relay picked up on the preceding impulse and a back contact of the stepping relay to be 50 picked up on the next succeeding impulse and a contact of said half-step relay closed during said 55 given impulse.

22. In a remote control system, in combination with a single line circuit energized with a series of time spaced impulses, said impulses being of selected long or short duration and said time spaces also being of selected long or short duration, a line relay operated to one position by said impulses and to another position by said time spaces, two timing devices one arranged to commence its operation when the line relay is moved to one position and the other arranged to commence its operation when the line relay is moved to its other position, said timing devices completing their operation if said line relay remains in the corresponding position for a long duration of time and failing to complete their operation if said line relay remains in the corresponding position for a short duration of time, a series of two-position polar relays having contacts which stay where put, there being a polar relay for 60 each of the time spaces and impulses, stepping 65

apparatus controlled by said line relay in response to the time spaces and impulses on said line circuit irrespective of their duration for sequentially establishing energizing circuits for the respective polar relays, and means for applying energy of one polarity or the other to each of said energizing circuits in turn as they are established in accordance with the long or short duration of the corresponding impulse or time space as determined by the operated condition of the timing device for that impulse or time space. 10

23. In a two-wire duplex code communication system of the type described for transmitting codes between a control office and a plurality of field stations, the combination with two line wires constituting a line circuit connecting the control office and the several field stations and a source of current in the control office for energizing said line circuit, of apparatus at each field station comprising, a changeable device having different conditions to be indicated in the control office, a sectionalizing relay governed by a change in the condition of said device for opening one line wire and connecting it to the other to terminate said line circuit at the corresponding field station, slow-acting means responding to the deenergization of said line circuit for deenergizing said sectionalizing relay after a predetermined time interval to extend the line circuit to more remote stations, means responsive to the flow of current in said line circuit after energization of said sectionalizing relay for maintaining that relay energized for a longer time interval, and code transmitting means adapted to govern the energization of said line circuit to form a code and condition it for operation only if said sectionalizing relay is energized and current is flowing in said line circuit at the corresponding station prior to the expiration of said predetermined time interval measured by 30 said slow-acting means. 35

24. In a code communication system for transmitting indications to a control office from any one of a plurality of field stations one at a time, a single line circuit connecting the control office 45 and the several stations, means at the control office for energizing said line circuit with one particular polarity while the system is at rest and responsive to an opening of said line circuit for changing the energization to the other polarity, a code transmitter at each field station operable to open and close said line circuit to form a code, cycle marking means at each field station including a slow-release relay assuming its deenergized condition after a prolonged deenergization of 50 said line circuit at the end of an operating cycle, said slow release relay being energized in response to the energization of said line circuit with said other polarity, a sectionalizing means at each field station operable when energized to terminate 55 said line circuit at that station, a changeable device at each station having different conditions to be indicated in the control office, an energizing circuit for said sectionalizing means rendered effective by a change in the condition of said device only if said line circuit is then energized with said particular polarity, a lockout relay governing the operation of the code transmitter and having a pick-up circuit energized by the flow of current in said line circuit at that station 60 after operation of said sectionalizing means, a stick circuit for said lockout relay closed by the energization of said slow-release relay, and time element means at each station initiated by deenergization of said line circuit by a field start 65 70 75

at any station for deenergizing said sectionalizing means at the corresponding station prior to the energization of said slow release relay unless said lockout relay is energized in response to flow of current in the line circuit after being section-
5 alized.

25. In a remote control system for transmitting control codes from a control office to any one of a plurality of field stations one at a time and simultaneously therewith transmitting indication codes from any given field station to the control office, a single line circuit connecting the control office and the several field stations, code transmitting means at the control office capable of being manually conditioned for determining the polarity of a series of impulses impressed on said line circuit comprising a code call for a particular one of the field stations and the controls for that station, normally-at-rest impulsing means for normally energizing said line circuit with one particular polarity while at rest, said impulsing means being initiated in response to a momentary opening of said line circuit for changing the energization of said line circuit to the other polarity and then operating to impress a series of time spaced impulses of such other polarity on said line circuit, said impulsing means also being initiated in response to a manual conditioning of said code transmitting means for changing the energization of said line circuit to said other polarity and then operating to impress a series of time spaced impulses on said line circuit of polarities determined by said manually conditioned code transmitting means in the control office, cycle marking means at each field station including a slow release relay initially energized only in response to the energization of said line circuit with said other polarity but remaining energized during a series of impulses irrespective of their polarities and assuming its deenergized condition after a prolonged deenergization of said line circuit at the end of a series of impulses, a sectionalizing means at each field station operable when energized to terminate said line circuit at that station after momentarily opening said line circuit, a changeable device at each field station having different conditions to be indicated in the control office, an energizing circuit for said sectionalizing means rendered effective by a change in the condition of said device only if said line circuit is then energized with said particular polarity, a lockout relay at each field station having a pick-up circuit energized by the flow of current in said line circuit during the operated condition of said sectionalizing means at that station if that station is the one nearest the control office having its sectionalizing means operated at that time, a stick circuit for said lockout relay closed by the energization of said slow release relay, means at each field station initiated upon the deenergization of said line circuit by the operation of the sectionalizing means at any station and subsequently rendered effective to cause said sectionalizing means to be deenergized to thereby complete said line circuit through all of said field stations for allowing the impulses of every series impressed by said impulsing means at the control office to be received at all field stations, code transmitting means at each field station rendered effective at the beginning of a series of impulses only if its associated lockout relay is picked up to modify said impulses of that series in accordance with the code call of that station and 70 the indications of the changeable device at such

station, and code receiving means at each field station responsive to the polarity of the impulses during a series for selecting that station if such polarities form the code call for that station, and code receiving means at the control office responsive to the modified impulses of any series for registering the station transmitting during that series and the indications transmitted from such station.

26. In a code communication system of the character described for a plurality of field stations, a single line circuit connecting a control office and the several field stations, a cycle marking slow-release relay at each field station initially energizable in response to the energization of said line circuit with a particular polarity and assuming its deenergized condition upon a prolonged deenergization of said line circuit, field start means at each field station for temporarily opening said line circuit and terminating it at that station, means in the control office acting to energize said line circuit with the other polarity while the system is at rest and responding to the temporary opening of said line circuit by operation of a field start means to energize the line circuit with said particular polarity, code transmitting means at each field station, and lockout means at each field station governed by the associated field start means and its cycle marking relay and responsive to the flow of current over said line circuit for rendering effective the code transmitter belonging to that station only if it is the nearest the control office among those stations having their field start means operated at that time.

27. In a multiple field station communication system, a single line circuit connecting the control office and the several field stations, a cycle marking slow-release relay governed by the energization of said line circuit and assuming its inactive deenergized condition whenever said line circuit is maintained opened for a prolonged interval, said cycle marking relay after deenergization thereof being initially energized only if said line circuit is energized with a particular polarity and after energization thereof being maintained energized by either polarity, field start means at each station operable upon a change in the condition of any device at that station to be indicated in the control office and effective only if said cycle marking relay is in its inactive condition and said line circuit is also energized at the time with the other polarity, said field start means operating to open said line circuit temporarily to create a field start condition in the control office and at all the other field stations, means in the control office for energizing said line circuit with said other polarity while the system is at rest, said means responding to a temporary opening of said line circuit by a field start at any station for reversing the polarity of energization of said line circuit to said particular polarity and thereby cause energization of the cycle marking relays at the several stations.

28. In a code communication system for transmitting indications to a control office from any one of two field stations one station at a time during an operating cycle, a single line circuit connecting the control office and the several field stations, a code transmitter at each field station operable to open and close said line circuit during an operating cycle to form an indication code characteristic of that station, cycle marking means including a slow release relay assuming its deenergized condition after a prolonged deener-

gization of said line circuit at the end of an operating cycle for restoring said code transmitter to its inactive condition, a changeable device at each field station having different conditions to be indicated in the control office, field start means at each field station responding to a change in the condition of said device at that station only if said cycle marking means is in its normal-at-rest condition and only if said line circuit is then energized with a particular polarity, said field start means temporarily opening said line circuit to create a field start condition in the control office, means in the control office for energizing said line circuit with said particular polarity while the system is at rest and responding to an opening of said line circuit by the field start means at any station for removing said particular polarity of energization, sectionalizing means at each station rendered effective by the operation of a corresponding field start means for terminating said line circuit at that station, and means at each station responsive to the flow of current in said line circuit at that station after operation of the corresponding sectionalizing means for governing the operation of the code transmitter at that station.

29. In a code type communication system; a normally energized line circuit connecting a control office and a plurality of field stations, said line circuit including a source of energy and a line relay at said control office; step-by-step means at the control office and at each field station operable through cycles of operation; cycle demarking relay means at the control office and each field station responsive to its respective line relay to be rendered active by a prolonged conditioning period marked off on said line circuit, to remain active during a following series of time spaced impulses on said line circuit, and to be rendered inactive by a prolonged deenergized condition of said line circuit for a clear-out period at the end of the series of impulses; circuit means at the control office and at each station rendered effective only when said cycle demarking relay means is active to cause said step-by-step means to be operated to take successive steps in synchronism in response to repeated energizations of said line relays; a plurality of changeable devices at each field station; transmitting means at each station effective when set into operation to cause a characteristic series of time spaced impulses to be impressed on said line circuit during a cycle of operation of said step-by-step means in accordance with indications of said changeable devices; initiating means at each station rendered active in response to a change in one or more of said devices at that station only if said line circuit is normally energized, said initiating means being effective when rendered active to open said line circuit; starting means responsive to the opening of said line circuit to mark off a prolonged conditioning period on said line circuit; lockout means at each field station, said lockout means being effective at those particular field stations having their initiating means rendered active, to determine during said conditioning period which one of such stations is to have its said transmitting means set into operation; and means effective at the end of a series of impulses to cause a prolonged deenergization

of said line circuit for a clear-out period and then close said line circuit for normal energization.

30. In a code communication system for transmitting indications to a control office from any one of a plurality of field stations one at a time, a single line circuit connecting the control office and the several field stations, means at the control office for energizing said line circuit while the system is at rest with one particular polarity, cycle marking means at the control office and at each field station assuming its inactive condition after a prolonged deenergization of said line circuit at the end of an operating cycle, changeable devices at the field stations having different operated conditions to be indicated in the control office, and apparatus at each field station comprising, a field start means initiated by a change in the operated condition of any device at that station and effective only if said cycle marking means is in its inactive condition and said line circuit is energized with said particular polarity, said field start means operating to open temporarily said line circuit to create a field start condition at the control office and at all of the other stations, code transmitting means operable to govern the energization of said line circuit to form an indication code characteristic of the corresponding station and the existing condition of its changeable devices, and lockout means initially conditioned by operation of said field start means at the corresponding station for rendering its code transmitting means effective for an ensuing cycle only if that station is nearer the control office than any other station having its field start means then operated.

31. In a code communication system for a control office and a plurality of field stations, two line wires constituting a line circuit connecting the control office and the several field stations, means in the control office for energizing said line circuit with a particular polarity while the system is at rest and operable in response to a deenergization of said line circuit to change the polarity, apparatus at each field station comprising, a code transmitter for opening and closing the line circuit during an operating cycle to form an indication code, cycle marking means including a slow release relay assuming its deenergized condition after a prolonged deenergization of said line circuit to restore said code transmitter to its normal at rest condition, said slow release relay being initially energized only by the other polarity, a field start circuit effective only after said line circuit is energized with said particular polarity, sectionalizing means governed by said field start circuit for opening one line wire extending to stations more remote from a control office and thereafter connecting that line wire to the other, a lockout relay acting if energized to render said code transmitter effective, means for initially energizing said lockout relay governed by said field start circuit and responsive to the flow of current in said line circuit at the station after operation of said sectionalizing means, and a stick circuit for said lockout relay closed by the energization of said slow acting relay.
